UNITED STATES PATENT OFFICE.

LAURENCE E. TOPHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,176,022.

Specification of Letters Patent. Patented Feb. 1, 1916.

Application filed April 15, 1911. Serial No. 621,286.

To all whom it may concern:

Be it known that I, LAURENCE E. TOPHAM, a citizen of the United States, residing at Beverly, in the county of Essex and State 5 of Massachusetts, have invented certain new and useful Improvements in Sewing-Machines; and I do hereby declare the following to be a full, clear, and exact description of the invention, such as will enable others 10 skilled in the art to which it appertains to make and use the same.

The present invention relates to sewing machines, and more particularly to wax thread lock stitch sewing machines which 15 employ a straight awl and a straight hook needle.

The object of the present invention is to produce a machine of the class referred to, having its various parts constructed and arranged 20 to operate in an improved manner so that the machine can be run at a high rate of speed without objectionable vibration and without excessive wear on the parts or liability of breakage, and so that the machine can produce as good, and in some respects, better, work than machines of the prior art.

The several features of the present invention will be clearly understood from an inspection of the accompanying drawings, in which a preferred embodiment of the invention is illustrated, and in which—

Figure 1 is a view in side elevation of the machine looking from the right; Fig. 2 is a view in side elevation of the machine looking from the left; Fig. 3 is a view in front elevation of the machine; Fig. 4 is a top plan view of the forward portion of the head of the machine; Fig. 5 is a view in front elevation of the head of the machine; Fig. 6 is a vertical sectional view taken on the line 6—6 of Fig. 1; Fig. 7 is a vertical sectional view taken on the line 7—7 of Fig. 1; Fig. 8 is a vertical sectional view taken on the line 8—8 of Fig. 1; Fig. 9 is a vertical sectional view taken on the line 9—9 of Fig. 5; Fig. 10 is a detail sectional plan view taken on the line 10—10 of Fig. 5; Fig. 11 is a detail sectional plan view taken on the line 11—11 of Fig. 5; Fig. 12 is a detail sectional plan view taken on the line 12—12 of Fig. 5; Fig. 13 is a detail view in front elevation taken partly in section, and illustrating particularly the take-up and thread retainer; Fig. 14 is a detail view taken partly in vertical section and particularly illustrating the upper end of the presser bar and its thread guiding eyes; Fig. 15 is a detail sectional plan view taken on the line 15 of Fig. 7; Fig. 16 is a side view looking 60 from the left, taken on a vertical central section, of the needle and rotary hook mechanisms; Fig. 17 is a top plan view of the needle and rotary hook mechanisms; Fig. 18 is a detail plan view of the rotary hook 65 and inclosed bobbin case, showing the beak of the hook just after it has entered the loop of needle thread; Fig. 19 is a sectional plan view taken on the line 19—19 of Fig. 16; Fig. 20 is a sectional plan view taken on the 70 line 20—20 of Fig. 3; Fig. 21 is a front elevation taken partly in section on the line 21 of Fig. 16; Fig. 22 is a detail front elevation taken partly in section, of the gimbal rings which oscillate the supporting frame 75 of the rotary hook; Fig. 23 is a detail sectional view on line 23—23 of Fig. 22; Fig. 24 is a view taken on a longitudinal cross section of the rotary hook, its supporting bearing, the bobbin case, and the detent pin 80 holding plate, the section of the fixed parts being that taken substantially on the line 24—24 of Fig. 18, while the cross-section of the rotary hook and bobbin case are on a different section from that of 24—24 of Fig. 85 18, the rotary hook being turned from the position shown in Fig. 18 so that Fig. 24 may better illustrate the bobbin retaining latch as well as the bobbin tripping and detent mechanisms and the bobbin ejecting 90 plunger; Fig. 25 is a view similar to Fig. 24 but with the rotary hook turned through half a revolution; Fig. 26 is a top plan view of the rotary hook and inclosed bobbin case, showing the rotary hook carrying the loop 95 of needle thread partly around the bobbin case; Fig. 27 is a plan view, taken partly in section, of the bobbin case, and particularly illustrating the thread tension spring; Fig. 28 is a sectional view of the bobbin case 100 taken on the line 28—28 of Fig. 27; Fig. 29 is a fragmentary view, taken partly in vertical section, of the rotary hook, the bobbin case being removed, and illustrating particularly the manner in which the loop of 105 needle thread is engaged by the beak of the rotary hook; and Fig. 30 is a detail view showing the spiral rib for the micrometer adjustment of the awl feed.

The work to be sewn is supported in the 110

machine by means of a flat work support formed by the throat plate 1 which is provided with the usual slot through which the needle and awl operate.

5 The presser-foot 2 which coöperates with the work support to position the work is of usual construction, and is secured to the lower end of a presser bar 3. During the greater part of the cycle of operations of 10 the machine the presser-foot is held against the work by the pressure of a comparatively heavy spring, so that the work is tightly clamped between the presser-foot and work support. During the feeding movement of 15 the work, however, the presser-foot is raised from the work so as to offer no resistance to the feeding movement. At the end of the feeding movement the presser-foot is released and is again pressed against the work 20 by said spring so that it has an opportunity to accommodate itself to the thickness of the stock. The presser-foot remains pressed against the work until the beginning of the next feeding movement, when it is again 25 lifted and the cycle of operations repeated. To enable the presser-foot to be actuated as above described, the presser bar 3 is slidably mounted in brackets 4 and 5 on the machine frame. The presser bar is kept from turning 30 in its sliding bearings by an arm 6 extending radially from it near its upper end, the outer end of which arm is bifurcated to slidably engage a pin 7 projecting upwardly from the bracket 4. The lower end 35 of the pin 7 is somewhat reduced to form a stud which is eccentric to the axis of the pin, and which is secured in a recess in the bracket 4 and clamped therein by a binder 8. The eccentric stud allows the pin 7 to be 40 turned to compensate for wear between the pin and the bifurcated arm 6. The means for automatically raising the presser-foot during each cycle of the stitch-forming operations, includes a collar 9 (Figs. 5, 9 45 and 11) slidably mounted upon the presser bar above the bracket 5. The collar 9 is provided with a forwardly extending ear or lug 10 which is bored to slide upon a pin 11 extending upwardly from the bracket 5. A 50 helical compression spring 12 surrounding the pin 11 between the enlarged head of said pin and the lug 10 tends to normally press the sleeve 9 down in contact with the bracket 5 which thus acts as an abutment 55 for the sleeve. The sleeve 9 is also provided with two lugs 13 which extend to the left, and between which is pivoted a lifting arm 14. When the free end of the arm 14 is raised, the arm 14 is first turned freely with 60 relation to the sleeve 9 which is held down by the spring 12, until a cam 15 (Fig. 11) which is formed on the inner end of said arm, is turned into gripping engagement with the presser bar 3 locking it in the 65 sleeve 9, after which the presser bar 3 and sleeve 9 are lifted together during the continuation of the upward movement of the arm 14. The arm 14 is oscillated by an adjustable link 16 which connects the free end of the arm 14 with the end of an arm 17 70 which extends radially from the forward end of a rock shaft 18. The adjustable link 16 is formed in two parts, the upper part forming a threaded socket for the reception of a screw-threaded pin 19 which forms the lower part of the link. The lower end of the screw-threaded piece 19 is bifurcated and is secured to the outer end of the arm 17 by a removable pin 20 which is held in place by a wire spring 21 which engages a 80 slot in the side of the projecting end of the pin 20. Adjustment of the link 16 is had by removing the pin 20, moving the link out of engagement with the arm 17, and adjusting the screw and socket connection. The 85 rock shaft 18 is journaled in the machine frame and is given an oscillatory motion by means of an arm 22 extending radially from the rear end of the rock shaft (Fig. 12), which arm carries a roller 23 running in a 90 cam path cut in the front face of a cam wheel 24 mounted upon the continuously rotating shaft 25. The shaft 25 is journaled in the machine frame and is driven from the vertical shaft 26 by means of a gear 95 wheel 27 (Fig. 8) meshing with a spiral gear 28 on the shaft 26. The vertical shaft 26 is in turn driven from the main driving shaft 29 by means of bevel gears 30. The normal direction of rotation of these driving shafts is indicated by arrows in various figures of the drawings. The timing of the cam path which oscillates the rock shaft 18 is such that the rock shaft 18 is oscillated to lift the arm 14 to raise the presser-foot 105 just before the feeding movement of the work takes place, and to lower the arm 14 to release the presser-foot after the completion of the work-feeding movement. When the arm 14 is in its lowered position, the sleeve 9 is pressed against the bracket 5 110 and the presser bar is free to adjust itself in accordance with the varying thickness of the work, so that, when the arm 14 is afterward raised, it will grip the presser bar in whatever position the presser bar may be and lift the presser-foot a predetermined distance from the surface of the work, regardless of the thickness of the work. A fixed amount of motion is communicated to the lifting arm 14, but the amount of lifting movement imparted to the presser bar 3 may be varied by adjusting the inclination of the arm 14 by means of the adjustable link 16. By shortening the link 21, the amount of 115 free movement of the lifting arm 14 before its cam-shaped end 15 grips the presser bar will be increased, and the amount of lift imparted to the presser-foot will be correspondingly decreased, since only the lifting 120 125 130

movement of the arm 14 after the cam has gripped the presser bar is effective to raise the presser bar.

To enable the presser-foot to be raised by the operator with the parts of the machine in any position which they assume during a cycle of operations, and particularly when the parts are in a position to permit the removal or insertion of work, a treadle is provided and suitable connections whereby the presser-foot may be raised at the will of the operator. To enable the presser-foot to be thus raised the upper end of the presser bar is offset rearwardly to form an upwardly extending plate 31 which is provided with a horizontal forwardly extending ledge or shoulder 32 (Figs. 9 and 14). This shoulder 32 engages over the top of a round finger 33 which extends rearwardly from the extreme end of a lifting arm 34 and which also bears against the flattened top of the main portion of the presser bar. The shoulder 32 and the flat upper surface of the main portion of the presser bar thus form between them a laterally extending slot for the reception of the finger 33, so that when the arm 34 is lifted it will raise the presser bar. The arm 34 is formed on a sleeve 35 which is rotatably mounted upon a pin 36 which forms the forward bearing of a rock shaft 37 (Fig. 10). The rear end of the sleeve 35 has formed in it notches or recesses 38 in which are engaged forwardly projecting lugs 39 on the rock shaft 37. The lugs 39 are sufficiently smaller than the notches 38 to allow the sleeve 35 enough lost motion with relation to the rock shaft 37 so that the lever arm 34 is free to turn idly about its bearing on the pin 36 when the presser bar is raised and lowered by the automatically operated lifting arm 14 during the normal operation of the machine. The rock shaft 37 is turned to raise the arm 34 and presser bar 3 by means of a sliding bar or rod 40 (Fig. 8) secured to the laterally projecting arm 41 of a bell crank lever 42 rigidly mounted upon the rear end of the rock shaft. The sliding bar 40 is drawn downwardly by a wire 43 running to a suitable treadle, not shown. In order to raise the treadle after it is released by the foot of the operator, a helical compression spring 44 is coiled about the rod 40 between the enlarged upper end of said rod and a plate 45 which is secured to the machine frame, and through which the bar 40 is slidably received. When the operator depresses the treadle, the wire 43 is drawn down, turning the rock shaft 37, which by means of the lug-and-notch connection 39 and 38 raises the arm 34 to lift the presser bar. At the time when the needle and awl are out of the work and permit its easy removal the lifting arm 14 is in its downwardly turned position and out of its gripping engagement with the presser bar so that the presser bar is free to slide up and down through the sleeve 9 which is held down against the bracket 5 by the spring 12. The presser bar may, however, be raised by the treadle when the machine is at any position in its cycle of operation. If the treadle is depressed to raise the presser bar when it is gripped in the sleeve 9 by the lifting arm 14, the presser bar 3 and sleeve 9 will be lifted together until the arm 14, whose outer end is held by the link 16, is turned sufficiently to disengage its cam-shaped end 15 from the bar, after which the sleeve 9 will be no longer raised, but the presser bar will be freely lifted through said sleeve. The downward pressure which normally holds the presser foot against the work is supplied by a comparatively heavy helical spring 46 (Fig. 10) wound over the rock shaft 37, the forward end of which spring is extended laterally and bears down upon the finger 33 of the arm 34, and the rear end of which spring is secured to the forward end of a sleeve 47 rotatably carried upon the rock shaft 37. For convenience of construction the sleeve 47 is formed of the front and rear portions, which are secured against rotation relatively to each other under the action of the spring 46 by means of a toothed connection 48 (Fig. 4). Gear teeth 49 are cut in the rear portion of the sleeve 47 and mesh with a worm cut on a shaft 50 which is adapted to be manually turned by means of the handle 51 to adjust the tension of the spring 46 against the presser bar.

The work is fed through the machine from right to left by means of a straight awl indicated at 52. The awl is secured by means of clamping screw 53 (Fig. 5) in a socket formed in the lower end of a vertically reciprocating awl carrier or bar 54. The awl bar 54 is slidably mounted in a box or carrier 55 which is hung from the machine frame and is maintained in vertical alinement therewith by means of an arm 56 and twin lever arms 57 and 58 which are parallel to the arm 56 (Figs. 2 and 5). The lever arms 57 and 58 are power oscillated to impart a lateral swinging movement to the carrier 55 and the arm 56 acts as a link to cooperate therewith in maintaining the alinement of the carrier. The arm 56 projects from a rock shaft 59 (Figs. 9 and 11) which is free to turn upon pivot pins 60 and 61 mounted on the machine frame and is pivotally connected at 62 to the upper end of the carrier 55. The twin lever arms 57 and 58 which move the carrier 55 are formed integrally with a power oscillated rock shaft 63 (Fig. 2) and are pivotally connected to the carrier 55 by means of journaled bear-

ings upon the pivot pins 64 and 65 which are clamped in the front and rear ends respectively of an elongated sleeve 66 formed integrally with the carrier 55. The two 5 somewhat separated bearings of the arms 57 and 58 upon the carrier 55 maintain said carrier from turning about a vertical axis. The rock shaft 63 is mounted at its front and rear ends upon pivot pins 67 and 68 re- 10 spectively secured to the machine frame. The rock shaft 63 has rigidly clamped upon it, near its rear end, a sleeve 69 formed with radially extending twin arms 70. The ends of the arms 70 are journaled upon project- 15 ing pins 71, which are clamped in a sleeve 72 formed on the lower end of a cam actuated swinging bar 73 (Figs. 2 and 7) which oscillates the rock shaft 63, the two separated bearings of the pins 71 serving to 20 maintain the bar 73 from turning about its longitudinal axis. The bar 73 (Fig. 7) is actuated by a cam roller 74 which is carried upon the upper end of said bar and which runs in a cam path cut in the rear face of 25 the cam wheel 75 (Figs. 1, 7 and 15) mounted on the forward end of the main driving shaft 29. The timing of this cam path is such that the feeding movement takes place while the awl is in the work. The bar 73 is 30 hung from a fixed pivot 76 by means of a link 77 which is pivotally secured to the bar 73 at 78 (Fig. 7). The pivotal connection 78 between the bar 73 and link 76 acts as a swinging fulcrum for the bar and is con- 35 strained to swing in the arc of a circle about the fixed pivot 76. The swinging fulcrum 78 allows the bar 73 to act in the combined capacity of a lever and a link, the pivotal connection 78 allowing the bar 73 to oscil- 40 late about it as a lever, while the link 77 allows the bar 73 to act as a link in transmitting the component of its movement in the direction of the arc of swing of the pivotal point 78 about the fixed pivot 76. 45 The other constraints on the bar 73 are the engagement of the cam roller 74 in the cam wheel 75 which actuates said bar, and the connection of the lower end of said bar to the rock arms 70 to which it imparts its 50 motion to actuate the awl feed. It will be evident that if the position of the fixed pivot 76 be adjusted, the consequent change in the arc of movement of the swinging fulcrum 78 will change the resultant movement im- 55 parted to the rock arms 70 and will therefore change the length of the lateral feeding movement of the awl. With this object in view, the fixed pivot 76 is carried upon the end of an arm 79 (Fig. 15) extending 60 radially from the forward end of a shaft 80 which is journaled in a bracket 81 formed on the inside of the machine frame and which is arranged to be manually turned to adjust the position of the fixed pivot 76. 65 The arm 79 and the link 77 (Fig. 7) are equal in length and the parts are so proportioned that when the bar 73 is raised to its highest position, the swinging fulcrum 78 will be co-axial with the shaft 80. The position of the awl at the completion of its 70 feeding movement corresponds to the raised position of the bar 73 and it is evident, since the swinging fulcrum 78 and shaft 80 are co-axial, that the turning of the shaft 80 to adjust the position of the point 76 will 75 not effect this position of the awl. When, however, the bar 73 is moved downwardly by the action of its driving cam, the swinging fulcrum 78 is swung from its co-axial position with respect to the shaft 80 and the 80 amount of turning which it imparts to the rock arms 70 at the downward limit of its movement will depend upon the position of the fixed pivot 76. The position of the awl at the beginning of its feed stroke corresponds to the downward position of the bar 73 and consequently this position of the awl will be varied by the manual adjustment of the position of the pivot 76. The awl will thus always be brought to the same 85 position at the completion of its feeding movement when it is withdrawn from the work for the entry of the needle into the awl hole, but the awl will have its position when it enters the work at the beginning of its 90 feeding movement varied laterally to produce the desired length of feed. 95 The shaft 80 is arranged to be manually turned to adjust the position of the pivot 76 by means of an arm 82 (Fig. 15) secured 100 to the rear end of said shaft and extending outwardly through an aperture 83 in the side of the machine frame. The end of the arm 82 is cylindrical in cross section, and is forwardly offset from and somewhat in- 105 clined to the main portion of said arm. This inclined end portion of the arm 82 is provided with a longitudinally extending recess 84 for the reception of a cylindrical plunger 85. The face of the projecting end 110 of this plunger is formed with a spiral rib 86 (Fig. 30) to engage a fixed segmental toothed plate 87 to hold the arm 82 in an ad- justed relation thereto. The plunger 85 is normally held against the toothed plate 87 115 by means of a helical compression spring 88, and is adapted to be either retracted against the spring or to be rotated by means of a knurled cap 89 which is secured to the pro- 120 jecting end of the reduced plunger shaft or pin 90. A gross adjustment of the awl feed is had by retracting the plunger 85 and turning the arm 82 with relation to the toothed plate 87, and a fine or micrometer adjust- 125 ment is had by rotating the plunger 85 which will cause the spiral rib 86 to carry the arm 82 slowly along the toothed plate 87. 130 In a lock-stitch wax-thread sewing ma- chine provided with a hook needle and an awl, it is desirable that as the awl retracts

the needle should follow the awl through the work as closely as possible so as to insure the entrance of the needle into the hole made by the awl. It is desirable that the movement of the awl should be so timed with relation to the other parts of the machine as to cause the awl to enter the work after the take-up has acted to pull the stitch into the work. The awl is thus out of the work while the stitch is being pulled in and the stock is not crowded over against the thread so as to partially close the last needle hole and prevent the thread from being drawn down properly into the work, as would be the case if the awl were in the work during the operation of the take-up. It is also desirable that the awl dwell in its advanced forward position in order that the awl may remain comparatively stationary in the work during its lateral feeding movement, and that the awl move rapidly when it punctures the work and when it leaves the work, and remain out of the work for a comparatively long period during each cycle of operations in order to avoid interference with the other working parts of the machine and to give as much time as possible for the thread handling devices to set the stitch. It is desirable that the needle advance quickly through the work, then remain as nearly stationary as possible while the looper and thread finger lay the thread in its hook, and retract quickly through the work, and that the needle dwell in its retracted position both in order that the needle may remain out of the work for a comparatively long time to allow for proper amount of time for the drawing in of the stitch and the feeding of the work, and in order that the needle may be comparatively stationary at the time when the loop taker enters the loop of thread drawn through the work by the needle. In machines as heretofore constructed it has been found necessary in order to produce these desired movements to drive the awl and the needle by means of cams. In the machine illustrated in the drawings improved mechanisms are provided for actuating the awl and needle which impart the desired movements to the awl and needle and which are easier and smoother in operation than the cam mechanisms heretofore used, and which are capable of being run at a higher rate of speed. The mechanism for actuating the awl consists of a continuously rotated crank and connections between the crank and the awl arranged to quickly push the awl through the work, to impart to the awl a dwell or a slight upward dip simultaneously with its lateral feeding movement, to quickly withdraw the awl through the work, and then to hold the awl out of the work for about 220° of a revolution of the driving shaft. The mechanism for actuating the needle consists of a continuously rotated

crank and connections between the crank and needle arranged to quickly advance and retract the needle through the work, to move the needle slowly at the forward turning point in the needle motion when the looper and thread arm operate to thread the needle hook, and to hold the needle in a backward or retracted position for about a half a revolution of the driving shaft, and to impart to the needle in its retracted position a dwell or slight upward dip so that the loop taker may with greater ease and certainty take the thread from the hook of the needle. These mechanisms operate in timed relation to each other and to the other parts of the machine so as to cause the awl to enter the work after the take-up has pulled in the stitch, and to cause the needle to follow the awl closely as the awl retracts through the work.

The mechanism for reciprocating the awl, while permitting it to move laterally to feed the work, comprises a link 91 (Fig. 5), the lower end of which is pivotally secured at 92 to the slidably mounted awl bar 54 and the upper end of which is pivotally secured at 93 to the end of an arm 94 projecting radially from the forward end of an oscillating rock shaft 95 journaled in the machine frame. The rock shaft 95 is oscillated by means of a reciprocating link 96 (Figs. 4, 6 and 9), one end of which is pivotally secured at 97 to an arm 98 projecting radially from the rear end of said rock shaft. The other end of the link 96 is journaled upon a crank pin 99 carried upon the front face of the cam wheel 75 which is mounted upon and continuously rotated by the main driving shaft 29. The rock shaft 95 and its two arms 94 and 98 act as an intermediate pivoted lever between the awl bar and the continuously rotating crank, the arms 94 and 98 being the power delivering and receiving arms respectively and the axis of the rock shaft 95 being the fulcrum. When the awl is at the lower or forward limit of its stroke the connecting point 93 is carried somewhat to the right of the position which it occupies as a dead center when the points 92 and 93 and the axis of the rock shaft 95 are in alinement. The movement of the point 93 to the right beyond its position as a dead center imparts a slight retractive movement or idle backward and forward movement to the awl at the limit of its downward or forward stroke. This slight retractive movement of the awl tends to lift the work slightly from the work support so that the awl may more easily carry the work to the left during its feeding movement which takes place after the awl has penetrated the work. The awl is moved comparatively rapidly as it passes through the work, so that as little time as possible is consumed by the awl in puncturing and

withdrawing from the work, and the awl bar carrier 55 is long enough to permit the back stroke of the awl to be lengthened to consume approximately 220° of a revolution of the driving shaft between the time that the awl leaves and enters the work. While in the machine illustrated in the drawings and embodying the invention in the preferred construction, the awl driving mechanism is so proportioned as to impart to the awl a slight upward movement while the awl is dwelling in its forward position, the present invention nevertheless contemplates within its scope such proportioning of the awl driving mechanism as to cause the awl to dwell in its forward position without a backward idle movement. Such a dwell without a backward idle movement can be secured in an awl driving mechanism like that illustrated by so proportioning the parts that the arm 94 and link 91 will be brought into alinement without having their connecting point 93 pass materially beyond a position of a dead center.

The needle 100 of the machine is a straight hook needle of the usual construction, and is removably clamped in the split upper end of a vertically reciprocating needle carrier or bar 101 by means of a clamping nut 102 (Fig. 16). The crank operated mechanism for actuating the needle comprises a bell crank lever 103 (Fig. 21), which is fulcrumed at 104 on a pin mounted on the machine frame, and one arm 105 of which is pivotally connected at 106 to a link 107, which is in turn pivotally connected at 108 to a collar 109 on the needle bar. The bell crank lever 103 is oscillated by means of a link 110, one end of which is pivotally connected at 111 to the second arm 112 of said bell crank lever, and the other end of which is connected at 113 to one arm 114 of a second oscillating bell crank lever 115 which is fulcrumed at 116 by two journal bearings 45 (Fig. 20) on the machine frame, in which is journaled the rock shaft which forms the axis of oscillation of the bell crank. The bell crank lever 115 is oscillated by means of a link 117, one end of which is pivotally connected at 118 to the second arm 119 of said bell crank lever, and the other end of which is journaled on a crank pin 120 carried by a continuously rotating crank 121 (Fig. 23) formed on the hub of a gear wheel 55 122 carried on the forward end of a horizontal shaft 123. The shaft 123 is rotated at the same speed as the main driving shaft 29 by means of the vertical shaft 26 and the bevel gears 124 (Fig. 1). About 180° of a revolution of the crank 121 are consumed by the advance, the looping, and the retraction of the needle, and the remaining 180° are consumed by the slight idle forward or backward movement or dip of the needle in its 60 retracted or backward position.

The link-work which connects the needle bar 101 with the crank 121 is so arranged that the needle is quickly advanced from its lower position through the work, is held comparatively stationary during the needle looping operation of the looper, and is then quickly retracted again to its lower position. When the needle is at the upward or forward limit of its stroke the connecting point 106 (Fig. 21) between the link 107 and bell crank 103 is moved nearly to the position of a dead center between the points 104 and 108, at which points the bell crank 103 is fulcrumed to the machine frame and the link 107 is connected to the needle bar 80 collar 109 respectively. The link 107 and the arm 105 of the bell crank 103 are thus brought nearly into alinement, and the momentary cessation of the movement of the needle when the crank pin 120 passes through its dead center position is consequently accentuated, so that the needle will be moved so slowly as to be comparatively stationary during the time taken by the operation of the looper. This pause in the motion of the needle acts substantially as a dwell in allowing the looper to lay the thread in the hook of the needle with greater ease and certainty than if the needle were reciprocated with a simple harmonic motion, 90 especially if the operating parts become somewhat worn by use. The substantial dwell, which the needle has at its upward limit of its movement, also performs an important function in preventing an overthrow of the needle when the machine is running at high speed. The overthrow of rapidly driven needles of the crank-operated type is principally due to the bending of the lever arms in the needle-actuated 95 mechanism under the strain imposed upon them in checking the momentum of the needle bar when its direction of motion is suddenly changed at the limit of its stroke. Since the needle of the present invention 100 substantially dwells at the upper limit of its stroke, the needle is moved comparatively slowly through this turning point of its motion, and the strain put upon the needle actuating lever arms is correspondingly 105 lessened. Moreover, when the needle is raised, the link 107 and the arm 105 of the bell crank 103 are nearly in alinement, so that this arm of the bell crank is subjected to very little bending strain, the direction 110 of strain being mostly along the axis of said arm and against its bearing 104. With the parts in this position the movements of the other lever arm of the link work impart very little movement to the needle bar, so 115 that whatever overthrow these other lever arms have as a result of stopping the needle bar and of checking their own momentum, will have very little effect in causing the needle to overthrow. illustrated in the drawings and embodying the invention in the preferred construction, the needle driving mechanism is so proportioned as to hold the needle nearly stationary during the operation of the looper, the present invention nevertheless contemplates within its scope such proportioning of the needle driving mechanism as to impart to the needle an absolute dwell, or even a slight dip in its movement during the operation of the looper. Such a dwell or dip in the needle motion can be secured in a needle driving mechanism like that illustrated by so proportioning the parts that link 107 and the arm 105 of the bell crank 103 will be brought into full alinement, or even beyond a position of alinement when the needle is at the upper limit of its stroke. During a cycle of operations the needle is twice at the extreme downward limit of its movement, namely, immediately after it has completed its downward loop-drawing stroke, and just before it begins its upward work-piercing stroke. These two downward limits of the needle motion are approximately 180° of a revolution of the crank 121 apart, and in both of these positions the pivotal connecting points 111, 113 and 116 are in alinement. The connecting link-work is so arranged that after the needle is drawn to its downward limit at the completion of its loop-drawing stroke, the bell crank 115 continues its movement to the left, carrying the point 113 upwardly and to the left somewhat beyond the position in which it was in alinement with the points 111 and 116. This imparts to the needle a slight idle movement or dip which occupies the 180° during which the needle is held in its retracted position. This slight upward dip of the needle serves to hold the loop of needle thread practically stationary for a comparatively long time, so that not only does the beak of the loop taker operate on a loop which is held stationary for its entry therein, but also will continue to act with precision and certainty in entering the loop even if the initial accurate timing of the needle and loop taker has been impaired by the wear of these parts, advantages which it is impossible to attain with the crank operated needles hitherto constructed in which the beak of the loop taker enters the thread loop when the needle is moving rapidly. While in the machine illustrated in the drawings and embodying the invention in the preferred construction, the needle driving mechanism is so proportioned as to impart to the needle a slight upward movement while the needle is dwelling in its retracted position, the present invention nevertheless contemplates within its scope such proportioning of the needle driving mechanism as to cause the needle to dwell in its retracted position without a forward idle movement. Such a

dwell without a forward idle movement can be secured in a needle driving mechanism like that illustrated by so proportioning the parts that the bell crank arm 114 and link 110 will be brought into alinement 76 without having their connecting point 113 pass materially beyond a position of a dead center.

The needle is provided on its side with the usual thread receiving hook or bar. After the needle passes up through the work the thread is laid in the barb of the needle by means of a looper 125 and a coöperating thread finger 126. These parts have substantially the same motions and mode of operation as the looper and thread finger ordinarily used in straight needle lock stitch machines. These parts are, however, mounted in the machine in a somewhat different manner, and are actuated by novel 85 mechanism.

The thread finger 126 (Figs. 6 and 12) is clamped upon the lower end of a short vertical rock shaft 127 journaled in the machine frame. The rock shaft 127 is oscillated by means of a link 128 which is connected between an arm 129 projecting radially from the upper end of said rock shaft and a sleeve 130 slidably mounted upon the shaft 63. The sleeve 130 is reciprocated on the shaft 63 by means of a cam roller 131 which runs in a cam path cut in the periphery of the cam wheel 24. The sleeve 130 is maintained from turning about its sliding bearing on the shaft 63 by means 100 of an upwardly projecting spline or tongue 132 (Figs. 2 and 6) which slides in a slotted plate 133 secured to the frame of the machine.

The looper eye 125 (Figs. 6, 9 and 12) is formed on the end of a forwardly extending looper arm 134 which is clamped to the lower end of a short vertical rock shaft 135. The rock shaft 135 is journaled in upper and lower bearings formed in the arms 136 and 137 of a double-yoke-shaped carrier 138 which is secured to the machine frame to oscillate about a vertical axis by means of two pivot pins 139. The looper has a compound motion in laying the thread in the 115 barb of the needle. One component of the compound motion of the looper is provided by the oscillation of the rock shaft 135 in its bearings to impart a lateral swing to the looper arm 134, while the other component of the looper motion is provided by the oscillation of the carrier 138 about its pivot pins 139 to bodily move the rock shaft 135 forwardly and rearwardly. The means to oscillate the rock shaft 135 in its bearings 120 comprises an arm 140 clamped to said rock shaft between its journal bearings in the arms 136 and 137, a connecting link 141, and a reciprocating sleeve 142 which is slidably mounted on the shaft 63 and is recip- 130

located by means of a cam roller 143 which runs in a cam path cut in the periphery of the cam wheel 24. The sleeve 142 is maintained against turning on the shaft 63 by means of an upwardly projecting spline or tongue 144, which slides in the slotted plate 133. The means for oscillating the carrier 138 to provide the second component of the looper motion comprises an arm 145 projecting from the carrier, a connecting link 146 (Fig. 9), and a reciprocating bar 147 which is slidably mounted in the machine frame and is reciprocated by means of a cam roller 148 which runs in a cam path cut in the periphery of the cam wheel 24. The bar 147 is maintained against turning in its sliding bearings by means of a projecting arm 149, the bifurcated end of which slides on the edge of a guide plate 150 secured to the machine frame. The cams which actuate the looper are so timed that the looper is given the usual movement in this class of machines to present the thread to the thread finger and then lay the thread in the barb of the needle.

The loop taker of the machine by which the loop of thread drawn through the work by the needle is passed over the locking or bobbin thread is of novel construction and is arranged and operated in an improved manner. This loop taker is in the form of a continuously rotating internal hook and is arranged to pass the loop of thread around a stationary bobbin case without itself passing through the loop. This hook is rotated continuously by means of simple and compact mechanism at a uniform rate of speed three times as great as that of the crank which operates the needle, and is so constructed and arranged as to permit the use of simple and efficient means for supporting the bobbin case and permitting the loop of needle thread to be passed around the bobbin case. The hook makes three revolutions during each cycle of operations in order that only about one-third of the cycle need be taken by the operation of passing the thread over the bobbin case and the remaining two-thirds of the cycle may be devoted to the other stitch forming operations. The hook can be operated at a high rate of speed without liability of injury to its actuating mechanism and without setting up objectionable vibrations in the machine frame and the parts supported thereby. Furthermore the hook is placed in the machine in such a position with relation to the other operating parts, and particularly with relation to the needle and the work supporting throat plate, that the hook and its actuating mechanism do not interfere with the manipulation of the work by the operator or its ready inspection at all times, that the hook draws off as short a loop as possible in passing the loop of needle thread

over the bobbin case, that the hook takes the loop of needle thread from the barb of the needle with ease and certainty, and that the hook allows the loop of needle thread to be readily cast therefrom after the loop has been passed around the bobbin case.

As illustrated in the drawings (Figs. 16 to 29), the loop taker consists of a continuously rotating internal hook, indicated as a whole by the reference character 151, which is provided with an internal or inwardly directed beak 152. This rotating hook has the general form of a short hollow cylinder or ring, which is peripherally supported and driven so that it can be rotated while the needle is passing through it without striking the needle. The hook is rotatably supported by means of an inwardly extending peripheral flange 153 at its lower end which engages in a peripheral groove or raceway formed between the edges of two circular plates 154 and 155 which are secured to the upper part of a hook supporting frame or carrier 156. The hook is thus supported just beneath the work support 1 and in a plane which extends backwardly and downwardly from the work support at an angle of about 30° to the plane of the work support or 60° to the needle. This allows a comparatively narrow work support or throat plate to be employed and gives free space both in front of and behind the work support so that the work may be readily manipulated by the operator and at the same time so positions the rotary hook that its beak engages the loop of thread just beneath the throat plate aperture in order that as short a loop of needle thread as possible will be drawn out by the hook. Easy access is provided to the hook and its inclosed bobbin by lifting a hinged cover plate 157, which lies just above and protects the hook. The rotary hooks of the prior art which lie in a substantially horizontal plane beneath the work support present the advantage of easy accessibility for the inspection of the hook and the removal of the bobbin, but possess the disadvantage inherent in horizontally arranged hooks of taking the loop of thread away from the needle at substantially right angles to the needle shaft. When the loop of thread is taken from the needle barb in a direction at right angles to the needle, the thread is liable to be cut or raveled by the sharp point of the barb. The rotary hooks of the prior art which lies in a substantially vertical plane beneath the work support present the advantage over horizontally positioned hooks of taking the thread out of the barb of the needle in a direction extending back along the shaft of the needle so that the thread is not caught by the point of the needle barb, but possesses the disadvantage, compared with horizontally positioned hooks, of being so positioned with relation

to the work support that access to the hook is much more difficult. The rotary hook of the present invention, which is inclined at substantial angles to both the plane of the work support and axis of the needle, combines the advantages of both the horizontal and vertical types of hooks. Easy access is provided from above for the inspection of the hook and the removal of the bobbin, and the hook is sufficiently inclined so as to pull the thread downwardly from the barb of the needle and avoid its being caught upon the point of the barb. A vertically extending aperture 158 is provided through the plates 154 and 155 and the hook supporting frame 156, so that the needle may pass up inside the ring-like body of the hook 151 and draw down a loop of thread. To enable the rotary hook to engage the loop of thread drawn down by the needle and pass the thread about the bobbin case, it is provided with a beak or nose 152 which is directed inwardly from the ring-like body of the hook. The inwardly directed projecting beak holds the thread on the inside of the ring-like body of the hook while the loop is being passed over the bobbin case. The beak is the only part of the hook which is interposed between the end of the loop and the work, so that a shorter loop of thread is drawn out in passing over the bobbin case than is drawn by an external type of hook, in which the beak is situated on the exterior of the hook body and necessitates that the end of the loop be carried upon the outer periphery of the hook body thus interposing a part of the hook body between the end of the loop and the work. The internal type of hook as herein employed enters the loop of thread drawn down by the needle and carries the loop about the bobbin case with a minimum amount of bending and twisting of the loop and reeving of the thread over the hook, and in this respect possesses important advantages over the external type of hook as applied to wax thread sewing machines. The hook is continuously rotated by a beveled gear wheel 159 which meshes with beveled gear teeth 160 cut upon the exterior of the lower end of the hook. The beveled gear 159 is connected through a universal joint 161 (Fig. 16) to a gear wheel 162 which meshes with the gear wheel 122 carried on the forward end of the shaft 123 which is rotated at the same speed as the main driving shaft. The gear wheels 162 and 122 are of a 1-3 ratio in size so that the hook 151 makes three revolutions during each cycle of stitch forming operations. One of these revolutions of the hook serves to carry the thread about the bobbin case, while the other two revolutions of the hook are idle. The first of these two idle revolutions takes place while the needle dwells in its retracted position, and the second takes place while the needle is moving upwardly

to penetrate the work. In order that the beak of the hook shall not strike the needle during this second idle revolution, the hook supporting frame 156 is slightly oscillated to carry the hook forward sufficiently so that the beak of the hook will pass in front of and clear the needle. The hook supporting frame 156 is mounted upon the machine frame by means of pivot pins 163 (Fig. 19) on either side of the universal joint 161 and having their axes passing through the center of said joint. 70

The mechanism for oscillating the hook-supporting frame 156 comprises a ring 164 (Figs. 20 and 23) which is horizontally 80 journaled on the machine frame by means of pivot pins 165 and which bears a forwardly projecting arm 166 which is connected to the hook carrying frame 156 by means of a vertical link 167. The ring 164 acts as a gimbal ring to pivotally support within it a second ring 168 which is free to oscillate on its supporting pivot pins 169 about an axis which lies at right angles to the axis about which the ring 164 oscillates 90 on its pivot pins 165. This gimbal-like mounting allows the ring 168 to be oscillated in all directions in such a manner that the oscillatory movement of the ring 168 about an axis drawn through the pivot pins 165 will oscillate the ring 164 and the hook-carrying frame 156, while the oscillatory movement of the ring 168 about its pivot pins 169 will not affect the position of the ring 164. A continuously rotating inclined flat cam plate 170 bears against the rear face of the ring 168 and oscillates said ring about the pivots 165 and 169 with a wobbling motion, or the movement which the ring 168 would have if it were held from rotating with but constrained to lie in a plane which was inclined to and continuously rotated about an axis passing through the center of the ring. The cam plate 167 is formed on the rear end of a shaft 171 and lies in a plane inclined to the axis of said shaft. The shaft 171 is journaled in the machine frame co-axially with the driving shaft 123 from which it is continuously rotated by means of a crank arm 172 formed on the shaft 171 and bearing a pin 173 which engages in a socket formed in the end of the crank pin 120 which drives the needle mechanism. The inclined cam plate 170 and the pivotally mounted rings 168 and 164 act to transform the continuous rotary motion of the driving shaft 123 to an oscillatory movement of the hook carrying frame 156. 110

Within the upper part of the ring-like body of the rotary hook 151 is supported a stationary or non-rotatable discoidal bobbin case 174 (Figs. 24 and 25). The bobbin case has an annular groove or raceway 175 cut upon its periphery and is rotatably supported with relation to the rotary hook in a 120 125 130

plane somewhat inclined to the axis of rotation of said hook by means of an annular plate or ring 176 which is secured to the inclined top of the rotary hook body and engages in the annular groove 175. The ring 176 extends nearly in a complete circle, only the portion of the ring which is adjacent to the thread receiving groove of the hook being cut away (Figs. 18, 26 and 29). One edge of the bobbin case is notched at 177 (Figs. 26 and 27) to provide an aperture in alignment with the aperture 158 for the upward passage of the needle between the bobbin case 174 and the interior of the ring-like hook 151.

The mechanism which retains the bobbin case from rotating and at the same time permits the loop of needle thread to be carried about it, comprises downwardly projecting detent pins 178 (Figs. 24 and 25) which are adapted to engage in recesses 179 cut in the top of the bobbin case near its outer edge. The detent pins 178 are mounted upon a plate 180 which is rigidly supported upon the hook supporting frame 156 by means of studs 181 which are mounted upon arms 182 projecting from the circular plate 155. A circular aperture 183 is cut through the plate 180 to allow for the removal of the bobbin. The rotation of the hook 151 imparts a wabbling or tilting motion to the bobbin case 174 which is held stationary against rotation in a plane which is inclined to and is continuously rotated about the axis of rotation of the hook. This wabbling motion causes one edge of the top of the bobbin case to be elevated to bring at least one of the recesses 179 into engagement with the detent pins 178 to hold the bobbin case from rotation. As the hook rotates, the point at the edge of the upper surface of the bobbin case which is momentarily elevated travels continuously around the bobbin case, moving with a rolling motion with relation to the detent plate 180. The edge of the top of the bobbin case which is opposite said elevated point is, in consequence, always tilted downwardly from engagement with the detent pins 178 so that a free thread clearance space is provided which continuously travels between the bobbin case and the detent plate in the direction of rotation of the hook. The inclined supporting ring 176 is so positioned with relation to the beak 152 of the rotary hook that this thread clearance space is adjacent the beak. As the beak 152 travels around the bobbin case, one leg of the loop of the needle thread is carried over the top of the bobbin case in the thread clearance space which travels between the top of the bobbin case 174 and the detent plate 180 adjacent the beak 152, the point of engagement between the bobbin case and pins 178 retreating before the advance of the thread. The foregoing mechanism for holding the

bobbin case from rotation is very simple and efficient. The bobbin case is positively moved to provide a perfectly free clearance space for the passage of the thread and any cramping of the thread between the bobbin case and its detent and supporting devices is impossible. The hook and bobbin case are moved with motions which are continuously rotary or continuously rolling and there are no other moving parts so that the hook is adapted to be driven at a very rapid rate of speed without creating objectionable vibrations.

The manner in which the thread is passed about the bobbin case is clearly illustrated in Figs. 16, 18, 26 and 29. The beak 152 of the hook consists of a flat plate which is formed integrally with a block 184 (Figs. 16, 18, 26 and 29) secured to the body of the hook and which is offset below the main body of said block sufficiently to pass around beneath the edge of the lower face of the bobbin case. The outer edge of this flat plate is continued backwardly and outwardly from the point of the beak until at a point just outside the circumference of the bobbin case it merges with the lower end of a thread receiving valley or groove 185 which is formed between two forwardly and upwardly extending flanges 186 and 187 on the block 184. This groove is longer than the thickness of the bobbin case and extends from the lower face of the flat beak plate upwardly and backwardly so that its upward end is above the top of the bobbin case. The beak enters the loop of thread drawn down by the needle as illustrated in Figs. 16 and 18. The continued rotation of the hook draws the bight of thread along the outer edge of the beak plate and into a position in the thread receiving groove 185 outside the circumference of the bobbin case, as illustrated in Fig. 29. The leg of the loop which emerges from the lower end of the groove 185 is held below and is carried across the unobstructed lower face of the bobbin case, as illustrated in Fig. 26. The leg of the loop which emerges from the upper end of the groove 185 is held above and is carried across the upper face of the bobbin case, the thread traveling in the clearance space provided for it by the wabbling motion of the bobbin case. The end of the beak is unobstructed so that when the beak approaches the needle receiving aperture 177, at the completion of the revolution of the hook, the loop of thread is pulled freely from the beak and into the work by the action of the take-up. The thread which forms that leg of the loop drawn through the work by the needle which is forward in position and which extends to the supply is engaged by the thread-receiving groove of the rotary hook and is carried by the hook around that thread which forms the other

or rearwardly positioned leg of the loop and which extends to the work, so that a half twist is put in the loop as it is pulled from the hook. However, as the loop is pulled 5 into the work this half twist is partly untwisted, so that when the stitch is set, the loop of the needle thread retains only the amount of twist which is necessary for it to have in lying over the bobbin thread at the 10 back of the stitch.

The top of the bobbin case 174 is provided with a cup-shaped bobbin-receiving recess 188 in which the bobbin is rotatably mounted upon an upwardly projecting stud 190 15 (Figs. 16, 24 and 25). The top of the stud 190 is provided with a transverse slot 191 of a cross section like an inverted T (Figs. 16 and 26) for the reception of a bobbin-retaining latch piece 192, which is provided 20 with a nose 193 engaging over the edge of the counter-sunk mouth 194 of the bearing aperture of the bobbin. The lower edge of the latch piece is flanged at 195 (Figs. 16, 24 and 25) to engage under the retaining 25 shoulders of the sides of the slot 191. At the end next the nose 193 the flanges 195 are of a depth equal to the depth of the enlarged lower portion of the slot, while at the opposite end the flanges are beveled off thinner 30 than the depth of said enlarged portion to allow them a certain amount of loose play up and down in said enlarged lower portion of the slot. The latch piece 192 is thus held to turn with a limited pivotal movement 35 about a point at the end of the lower enlarged portion of the slot which is next the nose 193, and is normally turned by means of a small helical compression spring 196 to hold the nose 193 outwardly to retain 40 the bobbin in place. Although the ends of the flanges 195 next the nose 193 are preferably made of a depth equal to the depth of the enlarged lower portion of the slot 191, it is evident that the latch piece could be 45 made with the flanges 195 thinner than the depth of the enlarged portion of the slot for their entire length, since the spring 196 at all times holds the top of the flanges up against the shoulders in the slot and the 50 latch piece would pivot with a thin flange at its end next the nose as well as with a flange at that point equal in depth to the enlarged portion of the slot. The spring 196 has a sufficient tension to cause the latch 55 192 to retain the bobbin in place during the operation of the machine, but allows the latch to turn when the bobbin is lifted by the manually operable bobbin-ejecting means.

The bobbin-ejecting means comprises an 60 ejecting plunger 197 which is adapted to strike the lower side of the bobbin through an aperture 198 cut through the bottom of the bobbin-receiving recess 188. The plunger 197 is formed with a rack 199 which 65 meshes with a pinion 200 (Fig. 16) jour-

naled in the hook-supporting frame 156. The pinion 200 is turned to raise the plunger 197 by means of a handle 201 (Fig. 21) which projects from the machine frame. A link 202 is connected by pin and slot connections to and forms a universal joint between the pinion 200, which is journaled in the movable frame 156, and the handle 201, which is journaled in a fixed part of the machine frame. A helical spring 203 surrounds the link 202 and is connected between the pinion and the machine frame. This spring acts both as a compression spring to retain the pinion 200 in place and as a torsion spring to turn the pinion to automatically retract the ejecting plunger when the handle 201 is released by the operator. The notch 177 in the edge of the bobbin case, through which the needle passes, is at one point extended through the wall of the bobbin-receiving recess 188 to provide an open-topped lateral opening 204 (Figs. 26, 27 and 28) for the passage of the thread from the bobbin. The inner face of the bobbin-receiving recess 188 at one side of the opening 204 is provided with a short thread guiding groove 205 over which is pressed the upwardly extending finger 206 of a thread tension spring 207. The top of the finger 206 is bent slightly away from the surface of the bobbin-receiving recess, so that the thread may be easily slipped down between it and the wall of said recess. The other end of the spring 207 is provided with an upwardly extending half-round stud 208 which is engaged in a correspondingly shaped recess in the wall of the bobbin-receiving recess and is adapted to be turned by a clamping screw 209 to adjust the tension of the spring on the thread. The above arrangement of parts permits the bobbin case to be easily threaded. In threading the bobbin case a short length of thread is taken from the bobbin and is drawn down between the end 206 of the tension spring and the wall of the bobbin receiving recess 188 into the thread groove 205. The free end of the thread is then passed into the thread guiding eye 210 through a slot 211 provided for that purpose. After the bobbin case is thus threaded, the bobbin is inserted in its receiving recess, the thread passing from the eye 210 directly to the work. Although the steps of threading the bobbin case may be carried out in a different sequence than as above described, yet this is in general found to be the most convenient method.

The devices for controlling and handling the needle thread, in addition to those already described, comprise a tension, a pull-off, a take-up, a thread detainer, and two thread locks, one of which locks the thread between the take-up and the pull-off, and the other of which locks the thread between

the pull-off and the supply. These parts are constructed and arranged to operate in an improved manner and are actuated by novel mechanism.

5 The tension device comprises a thin circular plate or wheel 212 (Figs. 5 and 9) the edge of which is formed with serrations which are alternately offset to form a peripheral thread receiving groove in which 10 the thread is held from slipping relatively to said wheel. The wheel 212 is loosely mounted to rotate on a bar 213 (Fig. 5) which is slidably mounted in a bracket 214 projecting upwardly from the head of the 15 machine. A suitable friction device is provided for retarding the rotation of the wheel 212 so that a strain or tension may be put upon the thread as it is drawn from the work side of the tension device. The friction device comprises two friction disks or 20 brakes 215 and 216 between which the wheel 212 is adapted to be clamped. The friction disk 215 is secured to one side of the bracket 214 and the friction disk 216 is slidably 25 splined upon the bar 213. The right end of the bar 213 is somewhat reduced to form an annular shoulder or abutment 217 which is adapted to be engaged by a corresponding shoulder formed on the interior of the hub 30 of the friction disk 216 and limit the movement of the disk 216 to the left on the bar 213. A helical compression spring 218 extending between the disk 216 and a knurled nut 219 on the end of the bar, normally 35 presses the disk 216 against the stop shoulder 217, except at such times as the bar 213 is drawn to the left to apply the disk 216 directly to the side of the wheel 212. When the bar 213 is drawn to the left, the disk 216 40 is brought against the side of the wheel 212, and the continued movement of the bar 213 withdraws the shoulder 217 from its engagement with the disk 216 so that the wheel 212 is frictionally clamped between 45 the brake disks 215 and 216 to put a tension on the thread as it is drawn over the wheel 212. The degree of tension put on the thread may be varied by adjusting the tension of the spring 218 by means of the nut 219. When it is desired to relieve the thread 50 of the strain put on it by the friction device, the bar 213 is released, whereupon the spring 218 will draw the bar 213 to the right until the stop shoulder 217 is brought into engagement 55 with the disk 216 and relieves the wheel 212 from the pressure of the disk 216 so that it may be freely turned. The means for actuating the bar 213, as above described to apply and release the friction device, 60 comprises a vertical lever 220 pivotally secured to the left end of the bar 213 and fulcrumed against the point of an adjustable pin 221 on the side of the bracket 214. The lower end of the lever 220 is formed with a ball 65 222 which is received in a cylindrical recess 223 in the top of a sleeve 224 which is mounted upon the forward end of a rock shaft 225. The rock shaft 225 is oscillated to actuate the lever 220 through the ball-and-recess connection and operate the friction device 70 as above described. The ball-and-recess connection also holds the lever 220 from moving forwardly or backwardly, and so maintains the bar 213 from turning in its sliding bearing in the bracket 214. The rock shaft 75 225 is oscillated by means of a radially extending arm 226 mounted upon its rear end (Figs. 4 and 8). A bell crank lever 227 is pivoted at its elbow to the end of the arm 226. One arm of the bell crank lever 227 is pivotally connected at 228 to one end of a link 229, the other end of which is pivotally connected at 230 to the upwardly extending arm 231 of the bell-crank lever 42 which is adapted to be turned by the pressure foot 80 lifting treadle hereinbefore described. The other arm of the bell-crank lever 227 is pivotally connected at 232 to one end of a link 233, the other end of which is pivotally connected at 234 to an arm 235 extending from 85 a rock shaft 236 (Figs. 1, 4 and 8). The rock shaft 236 is journaled in the machine frame and is oscillated by a downwardly extending arm 237 which carries a cam roller 238 running in a cam path cut in the rear 90 face of the cam wheel 239. During the normal operation of the machine the connecting point 230 is stationary and the bell-crank lever 227 fulcrums about the point 228 so that the motion of the cam actuated arm 237 95 is transmitted through the shaft 236, the arm 235, the link 233 and the bell-crank lever 227 to oscillate the rock shaft 225 to apply and release the friction device of the thread tension once during each cycle of the stitch forming 100 operations. The oscillation of the rock shaft 225 is constant in amount and is timed by the cam wheel 239. The timing of the application and release of the tension put upon the thread by the friction device may be 105 varied within certain limits by the adjustment of the fulcrum pin 221 (Fig. 5) by which more or less lost motion is allowed between the lever 220 and the pin 221, and the period during which the thread is held 110 under tension shortened or lengthened respectively. The timing of the application and release of the friction device, with respect to the other operations of a stitch forming cycle, will be hereinafter described 115 with relation to the timing of the thread locks. In addition to the above described, automatic means to actuate the friction device, a manually operable release is provided. The manually operable release is actuated by depressing the treadle which raises the presser foot and the friction on the thread tension is released simultaneously with raising of the presser foot, so that the 120 thread may be freely drawn out under no 125 130

tension when the work is removed from the machine. When the presser foot lifting treadle is depressed, the bell-crank 42 is turned to draw the link 229 downwardly and 5 to the right. This acts to turn the bell-crank 227 so that the toggle which is formed by one arm of the bell-crank 227 and the link 233, is broken and the arm 226 is moved downwardly to the left to turn the rock 10 shaft 225 and release the friction disks from the wheel 212.

The pull-off, by which during each cycle of the operations of the machine enough thread is pulled from the supply for the 15 formation of the succeeding stitch, is indicated at 240 (Figs. 5 and 10) and consists of a finger clamped to the right hand end of a rock shaft 241 horizontally and laterally journaled in the machine frame. The rock 20 shaft 241 is actuated at the desired times during the operation of the machine to cause the pull-off to pull off the desired amount of thread, by a long rearwardly extending link 242 (Fig. 1), the forward end of which 25 is connected at 243 to the end of the arm 244 projecting downwardly from the left end of the rock shaft 241 and the rear end of which is journaled upon a pin 245 adjustably secured in a curved slot 246 in the upwardly extending arm of a lever 247. The 30 lever 247 is fulcrumed by means of a pin journaled in a bearing 248 on the machine frame and is oscillated by a cam roller 249 which is carried upon the downwardly extending arm of said lever and runs in a cam path 250 cut in the periphery of the cam wheel 239. The slot 246 is of such a curvature that it lies in an arc of a circle struck about the point 243 as a center when the 35 rock shaft 241 is turned to move the pull-off finger 240 to the downward limit of its stroke. It is obvious, therefore, that the adjustment of the pin 245 in the slot 246 will not effect the downward limit of the stroke 40 of the pull-off finger. The adjustment of the pin 245 in the slot 246 will, however, vary the upward limit of the stroke of the pull-off finger, and so vary the amount of movement imparted to the pull-off finger. 45 The throw of the pull-off 240 is constant and in order to cause it to pull off the required amount of thread, which varies with the thickness of the material being stitched, the pull-off finger is arranged to pass between 50 two thread guiding eyes 251 and 252 through which the thread passes on its way from the tension device to the work. These eyes are formed directly on the upper end of the presser bar so that their position, with relation to the pull-off, is changed by any variation in the thickness of the work being operated upon. As will be apparent from an inspection of Fig. 5, the thread passes from the tension device downwardly through the 55 eye 251, then laterally across beneath the

pull-off finger 241 to the eye 252. The pull-off finger engages the thread between the eyes during its downward stroke and it will be obvious that since the stroke of the pull-off is constant, the amount of thread pulled from the supply by the pull-off will vary with the position of the eyes and more especially with the position of the eye 252. During its downward movement the pull-off 70 pulls threads from the supply through the eye 251 in the direction in which the thread leads through the eye, this eye acting merely as a thread guide to keep the thread at the right of the pull-off. The eye 252, therefore, forms the essential part of the thread measuring device since upon its position depends primarily the amount of thread pulled off by the pull-off, although the eye 251 performs an important and useful function in leading the thread to the eye 252 so that it 75 will be properly engaged with the pull-off. When the presser foot is raised, the eyes 251 and 252 are raised and a greater amount of thread will be pulled off between them by the downward movement of the pull-off 80 finger. If very thin work is being sewn and the pull-off is operated with its greatest stroke, only the latter part of the downward movement of the pull-off is effective in pulling off the thread. Hence, when thin work 85 is being sewn, the pin 245 is adjusted in the slot 246 to lessen the stroke of the pull-off so that the greater part of the pull-off stroke is utilized in pulling off the thread, whereby the thread is pulled more slowly 90 through the wax stripper and tension. 95

The main take-up is indicated at 253 (Figs. 5, 11 and 13) and consists of an arm secured to the forward end of a rock shaft 254 and provided at its free end with a take-up roll 255 which cooperates with the thread guiding rolls 256 and 257 to draw out a loop in the needle thread. To secure ease, smoothness and certainty of operation, when the machine is running at high speed, the rock shaft 254 carrying the take-up arm 253, is operated through suitable connections from a continuously rotating crank 258 (Figs. 4, 7 and 9), which is carried upon the front face of the cam wheel 75. To produce the proper timing of the awl and looper, the crank 258 is set somewhat in advance of the crank 99 (Fig. 7) although for convenience of construction, these two cranks are formed on the same projecting piece of metal. These connections (Figs. 4, 7 and 9) consist of an arm 259 upon the rear end of the rock shaft 254, a link 260 connecting said arm with an arm 261 carried by a rock shaft 262 which is journaled to the machine frame, and a link 263 connecting a second arm 264 on the rock shaft 262 to the continuously rotating crank pin 258. The rock shaft 262 and its arms 261 and 264 act as an intermediate pivoted lever between the take-up 100 105 110 115 120 125 130

up and the continuously rotating crank, the arms 261 and 264 being the power delivering and receiving arms respectively and the axis of the rock shaft 262 being the fulcrum.

5 The take-up arm 253 swings through an arc of nearly 180° and the arrangement of the connections above described for actuating the rock shaft 254 is such that the take-up moves very rapidly during its loop expanding stroke, turns quickly, and retreats rapidly, although not with such a rapid motion as during the loop expanding stroke, and then moves very slowly through the turning point of its movement between its retreat 10 and advance with a motion nearly approaching a dwell. It will be noticed from Fig. 13 that the take-up roll 255 is carried to the right beyond the position of the line of thread extending between the guide rolls 256 and 257. This allows the take-up to be 15 out of contact with the thread during the time consumed by the slow movement of the take-up in the neighborhood of its turning point. Sufficient time is consumed during 20 the retreat of the take-up and its slow movement before it again engages the thread, so that the time consumed by the take-up in expanding the thread loop is only about 80° of a revolution of the driving 25 shaft. This rapid loop expanding movement of the take up is necessitated by the fact that the hook makes three revolutions during each cycle of stitch forming operations and that the thread must be pulled 30 from the hook in about half a revolution of the hook. The movement of the take-up roll 255 when it engages the thread is at a substantial angle to the direction in which the loop is drawn out so that although the 35 take-up is beginning to move very rapidly when it first engages the thread, its action upon the thread loop is such that at the very beginning of the loop expansion the thread will be drawn comparatively slowly and 40 will not be subjected to a sudden snap or strain by the take-up. This allows the thread to be drawn in slowly just after it has passed over the middle of the bobbin case and before the rapid movement which 45 is necessary to draw it up along the side of the bobbin case and into the work. When the take-up is nearing the extremity of its loop expanding stroke, the take-up roll 255 is also moving in a direction which is greatly 50 inclined to the direction of the loop expansion so that the thread is drawn slowly during the final setting of stitch in the work. An oscillatory take-up arm, when operated at high speed, is liable to overthrow. To 55 prevent any overthrow of the take-up arm 253 having an appreciable effect upon the amount of thread in the loop pulled out by the arm during its take-up stroke, the arm 60 253 is arranged to reach a position approximately central with relation to the loop

which it draws out, this central position being the position of the greatest loop extension. Since the take-up roll 255 is moving in the neighborhood of its central position in an arc lying at nearly right angles to the direction in which it pulls out the thread loop, any overthrow of the take-up will have very little if any appreciable effect to further draw out the loop of thread. The take-up has a definite timed relation to the movements of the rotary hook which carries a loop of thread over the bobbin case and the needle and awl have a definite timed relation to the movements of the take-up and rotary hook, as hereinbefore described. 75

A slack thread controller or thread detainer, which comprises a thread engaging finger 265 (Figs. 4, 10 and 13) mounted upon the end of a short rock shaft 266, is provided to cooperate with the take-up to 80 properly deliver the thread to the looper, thread finger, needle, and rotary hook. With a crank operated take-up such as is illustrated in the drawing it is desirable that a thread detainer be employed as an auxiliary means to properly deliver the thread as required for the operations of the looper, thread finger, needle and rotary hook, rather than that the take-up driving mechanism should be so arranged as to cause 85 the take-up to perform this function. The thread detainer is operated to enter the loop of thread drawn out by the take-up at the time when the take-up has drawn the loop to its greatest extension to set the stitch in the work. When the take-up begins its return 90 movement, the loop of thread is caught and detained by the thread detainer, a slight retraction of the thread loop being allowed before it is caught by the thread detainer 95 so that the tension which was put upon the thread while the stitch was being set is relieved before the feeding operation of the awl begins, although without allowing the thread to become slack. After the thread 100 is engaged by the thread detainer, the thread detainer finger is moved to give up just enough thread to meet the requirements of the thread finger and of the looper as it lays the thread over the thread finger and into 105 the barb of the needle. After the needle is threaded the thread detainer continues to give up thread to meet the requirements of the needle as it descends to pull the thread into the work until the thread detaining finger is moved sufficiently to allow the thread to slip from the end thereof at a 110 time after the needle has drawn the thread into the work. 115

During the descent of the needle prior to the drawing of the thread into the work, the detainer delivers just enough thread so that the thread is held somewhat taut in the barb of the needle. After the thread 120 has been drawn into the work and the needle 125

is pulling out the thread loop below the work, the friction of the thread through the work serves to keep the thread taut in the barb of the needle, although the thread is slack above the work after it slips from the detaining finger. As is evident from an inspection of Fig. 13, the take-up thread roll 255 will, on its return stroke engage the length of thread extending between the 5 thread detaining finger 265 and the guide roll 257 and pull out thread between them. In order to compensate for this action of the take-up on its return movement, the detaining arm has a dip superimposed upon 10 the movements above described which is so timed that it gives up to the take-up the amount of thread drawn out by the take-up as it engages the thread, and then takes in the same amount of thread as the take-up 15 leaves the thread. The shaft 266 is oscillated to actuate the thread detainer as above described by means of cam actuated mechanism which comprises a rearwardly extending rock shaft 267 connected to the shaft 266 20 by means of beveled gears 268 and carrying upon its rear end an arm 269 (Fig. 1), and a link 270 connecting the arm 269 with an arm 271 mounted upon the forward end of a rock shaft 272 which is oscillated by means 25 of a second arm 273 carrying a cam roller 274 which runs in a cam path cut in the front face of the cam wheel 239. A curved guard plate 275 (Fig. 13) is provided to 30 form a thread guiding space between itself and the frame of the machine, in which the slack loop of thread pulled from the detaining finger is guided and kept from flying 35 forwardly and escaping the take-up roll 255 on its next succeeding loop expanding 40 stroke.

Front and rear thread locks indicated at 276 and 277 (Fig. 5) act intermittently during the cycle of operations to clamp the thread between the take-up and pull-off, and 45 between the pull-off and tension respectively. The front thread lock 276 closes so that the thread is clamped throughout the action of the pull-off, the rear thread lock at this time being open so that the thread may be 50 pulled through the tension by the pull-off. The rear thread lock 277 closes so that the thread is clamped throughout the action of the take-up, the front lock at this time being open so that the stitch is set against the 55 rear lock. The setting of the stitch against the rear thread lock pulls the thread taut through the thread guiding eyes of the pull-off and insures that no slack thread is left so that the proper amount of thread 60 will always be drawn by the pull-off through the tension. The thread locks are so timed that the thread is not released by one lock until after it is clamped by the other lock, so that the thread at no time is 65 free between the supply and the needle, and

the feed of the thread is perfectly controlled during the entire operation of the machine. The times at which the thread is held by both locks occur immediately after the operation of the take-up and immediately after 70 the operation of the pull-off.

The front lock, indicated generally by 276 (Fig. 5), consists of a thread roll 278 and a co-operating clamping shoe 279 which is adapted to grip the thread against the roll. 75 The clamping shoe 279 is formed on the lower end of a lever 280 pivoted at 281 to the frame of the machine. The mechanism for oscillating the lever 280 to actuate the thread lock comprises a rock shaft 282 (Fig. 80 9) which carries upon its forward end an arm 283 (Fig. 5) bifurcated at its free end to engage the lever 280 and which carries upon its rear end two laterally extending arms 284 and 285 (Figs. 7 and 9) bearing 85 on their free ends cam rollers 286 and 287 respectively, which run against two cam surfaces 288 and 289 formed side by side around the periphery of the cam wheel 75. These two cam surfaces 288 and 289 are so 90 proportioned relatively to each other that the rollers 286 and 287 are always adjacent their respective cams, so that no lost motion occurs between the rock shaft and these driving cams. The timing of the cams is 95 such that the clamping shoe 279 is moved to grip the thread just after the take-up has set the stitch and before the pull-off acts, and is moved to release the thread after the pull-off has drawn the thread from the 100 supply and just before the rotary hook draws out the loop which it passes over the bobbin case to its greatest extension. The thread handling parts are so arranged that the hook at this time pulls the thread just 105 taut, and so draws down the thread which has been taken from the supply by the pull-off.

The rear thread lock, indicated generally by 277 (Fig. 5), consists of a thread roll 110 290 over which the thread is carried in a complete turn and a co-operating clamping shoe 291 which is adapted to grip the thread against the roll. The clamping shoe 291 is formed on the free end of a laterally extending arm 292 integral with the sleeve 224 which is mounted on the rock shaft 225. The rock shaft 225 is oscillated as herein-before described under the operation of the friction device of the thread tension. During the operation of the machine the rock shaft 225 begins to turn to the right after the pull-off finger begins its descent. The rock shaft 225 is turned slowly enough to the right and the clamping shoe 291 has 115 sufficient motion relative to the roll 290, so that the thread is not gripped by the rear thread lock until after the completion of the pull-off stroke. The application of the friction device to the thread tension wheel 120 125 130

is preferably so timed that the pull-off will draw thread freely through the tension device during the first part of its stroke and will draw thread against the tension of the friction device during the last part of its stroke. Such timing of the friction device is attained by adjusting the fulcrum pin 221 so that as the rock shaft 225 is turned to the right the lever 220 will not engage against the fulcrum pin 221 and move the bar 213 to apply the friction device to the wheel 212, until the pull-off is nearing the completion of its stroke. The above timing of the friction device saves needless work on the part of the pull-off in drawing the thread from the supply under tension during the first part of its stroke, since it is only during the last part of the pull-off stroke that the tension is needed to insure that the thread be taut over the pull-off so that no extra thread will be stolen from the supply. Moreover, the application of the friction device while the wheel 212 is moving obviates the extra strain which would otherwise be put upon the thread in starting the wheel 212 against the static friction of the friction disks 215 and 216 which would be greater than is the moving friction of the wheel 212 against said friction disks. It is obvious, however, that the pin 221 may be so adjusted that the lever 220 will be in contact therewith when the rock shaft 225 begins its turning movement to the right so as to put the thread under tension during the entire stroke of the pull-off, if so desired. When the presser foot lifting treadle is depressed to raise the presser foot, the rock shaft 225 will be turned to the left, as hereinbefore described, and will release the clamping shoe 291 from the thread. The amount of turning imparted to the rock shaft 225 by the treadle will be sufficient to move the lever 220 out of contact with the pin 221 and so release the friction device from the thread tension wheel. When the machine is turned to free the work from the needle and awl so that it may be easily removed, the front thread lock is open, and the thread is thus entirely free to be drawn out from the supply as the work is removed from the machine.

The wax pot of the machine, indicated at 293, (Figs. 2 and 5), is mounted upon a bracket 294 on the top of the machine head. The thread is drawn from a ball or cop (not shown) into the wax pot through a guide tube 295, and is drawn from the wax pot to the thread tension wheel 212 through a suitable wax stripper 296. A second wax stripper projecting downwardly from the right of the wax pot and indicated at 297 is provided for delivering a second thread to any suitable bobbin winding attachment such as is usual to provide with this type of lockstitch machines.

The means for heating the machine comprises a steam supply pipe shown broken away at 298, which supplies steam to a steam chest 299 (Figs. 6 and 9) located in the top of the machine frame and extending 70 into the wax pot bracket 294. From the steam chest 299 the steam passes down through a pipe 300 to a steam chest 301 (Fig. 13) formed in the machine frame behind the thread roll 257. From the steam chest 301 the steam is conducted through a forward extending steam pipe 302 to a T connection 303. The upper arm of the T allows steam to rise into a blind heating pocket 304 (Fig. 13) in the bracket which supports the 80 thread detainer. The downwardly extending arm of the T connects with a long curved steam pipe 305 (Fig. 1) which carries the steam to a steam chest 306 formed in the frame of the machine at the rear of the bobbin and needle mechanisms. From the steam chest 306 the waste steam and water are conducted through a pipe, shown broken away at 307, to a suitable exhaust.

To provide for easy access to the hook 90 and the needle, the work support is arranged to be swung forwardly to expose the mechanism beneath it. The flat throat plate or work support 1 is supported by an arch cover or half round shell 308 (Figs. 16, 17 95 and 21) which is secured by the spline 309 and screw 310 to a pivoted plate 311. The plate 311 is pivoted to swing horizontally by means of a stud 312 journaled in the machine frame and is clamped in place by 106 means of a clamping bolt 313, the enlarged head of which engages over the upper edges of a V-shaped notch 314 (Fig. 17) in the rear of the plate. When the cover 308 is swung forwardly and the cover 157 is lifted 105 back, the needle and hook are entirely exposed for inspection or repairs. The spline and screw 309 and 310 are provided for the purpose of adjusting the position of the throat plate relatively to the needle and awl, 110 particularly to the awl. The awl 52 is in the work and projects through the elongated slot in the throat plate 1 during its lateral work feeding movement. During the maximum feeding movement of the awl, the awl 115 enters the elongated slot at the extreme right hand end of the slot, is moved to the left and is withdrawn from the extreme left hand end of the slot at the completion of its work feeding movement, the length of 120 the slot being equal to the distance between the center of the awl as it enters the work and the center of the awl as it is withdrawn from the work plus the radius of the largest size awl used added on either end of this 125 distance. As previously mentioned the awl is always brought to the same position when it is withdrawn from the work so that the center of the awl always occupies the same position at the end of its feeding movement. 130

It is evident, if the throat plate were fixed in position and a smaller size awl used, that owing to its smaller radius such an awl would not be brought to the extreme left end 5 of the slot in the throat plate. It is desirable, however, that the awl be brought to the extreme left end of the throat plate so that the stitch which has just been completed may be moved away from the slot and onto 10 a solid part of the throat plate. This is particularly desirable if a stitch impression tool be placed on the bottom of the presser foot. It is possible, however, by means of the screw and spline adjustment 309 and 15 310 of the present machine, to adjust the throat plate so that whatever size awl be used, the awl may be brought to the extreme left end of the throat plate and the last completed stitch be moved as far as possible 20 from the throat plate slot. By placing the spline and screw adjustment 309 and 311 between the arch cover 308 and the plate 1 it is possible to secure the throat plate 25 rigidly to the arch cover and to place its adjusting means at some distance away from the throat plate, thus leaving the throat plate entirely clear and allowing a larger and stronger spline and screw to be employed for adjustment than would be possible 30 to use if the throat plate were adjustable relatively to its supporting arch cover.

The invention having thus been described, what is claimed is:—

1. A wax thread lock stitch sewing machine, having, in combination, stitch forming devices including a hook needle, a continuously rotating loop taker, a take-up, an awl acting during each cycle of stitch forming operations to enter the work after the take-up has operated to set the stitch and leave the work as the needle enters the work, and continuously rotating cranks for actuating the needle, awl and take-up.

2. A wax thread lock stitch sewing machine, having, in combination, stitch forming devices including a hook needle, a continuously rotating loop taker, a take-up, an awl acting during each cycle of stitch forming operations to enter the work after the take-up has operated to set the stitch and leave the work as the needle enters the work, means for actuating the take-up, and continuously rotating cranks for actuating the needle and awl.

3. A wax thread lock stitch sewing machine, having, in combination, stitch forming devices including a hook needle, a continuously rotating loop taker, a take-up, an awl acting during each cycle of stitch forming operations to enter the work after the take-up has operated to set the stitch and leave the work as the needle enters the work, means for actuating the awl, and continuously rotating cranks for actuating the needle and take-up.

4. A wax thread lock stitch sewing machine, having, in combination, stitch forming devices including a hook needle, a continuously rotating loop taker, an awl acting during each cycle of stitch forming operations to enter the work after the take-up has operated to set the stitch and leave the work as the needle enters the work, means for actuating the needle, and continuously rotating cranks for actuating the awl and take-up.

5. A wax thread lock stitch sewing machine, having, in combination, stitch forming devices including a hook needle, a continuously rotating loop taker, a take-up, an awl acting during each cycle of stitch forming operations to enter the work after the take-up has operated to set the stitch and leave the work as the needle enters the work, means for actuating the take-up and awl, and a continuously rotating crank for actuating the needle.

6. A wax thread lock stitch sewing machine, having, in combination, stitch forming devices including a hook needle, a continuously rotating loop taker, a take-up, an awl acting during each cycle of stitch forming operations to enter the work after the take-up has operated to set the stitch and leave the work as the needle enters the work, means for actuating the take-up and needle, and a continuously rotating crank for actuating the awl.

7. A wax thread lock stitch sewing machine, having, in combination, stitch forming devices including a hook needle, a continuously rotating loop taker, a take-up, an awl acting during each cycle of stitch forming operations to enter the work after the take-up has operated to set the stitch, means for actuating the needle and awl, and a continuously rotating crank for actuating the take-up.

8. A wax thread lock stitch sewing machine, having, in combination, stitch forming devices including a hook needle, a continuously rotating loop taker making three complete rotations during each cycle of operations of the machine, a take-up, an awl acting during each cycle of stitch forming operations to enter the work after the take-up has operated to set the stitch and leave the work as the needle enters the work, and continuously rotating cranks for actuating the needle, awl and take-up.

9. A wax thread lock stitch sewing machine, having, in combination, stitch forming devices including a hook needle, a continuously rotating loop taker making three complete rotations during each cycle of operations of the machine, a take-up, an awl acting during each cycle of stitch forming operations to enter the work after the take-up has operated to set the stitch and leave the work as the needle enters the work,

means for actuating the take-up, and continuously rotating cranks for actuating the needle and awl.

10. A wax thread lock stitch sewing machine, having, in combination, stitch forming devices including a hook needle, an awl, a loop taker, a take-up, continuously rotating cranks, and lever and link connections between the cranks and the needle, awl and take-up.

11. A wax thread lock stitch sewing machine, having, in combination, stitch forming devices including a hook needle, an awl, a loop taker, a take-up, continuously rotating cranks, and lever and link connections between the cranks and needle and awl.

12. A wax thread lock stitch sewing machine, having, in combination, stitch forming devices including a hook needle, an awl, a loop taker, a take-up, continuously rotating cranks, and lever and link connections between the cranks and the needle and take-up.

13. A wax thread lock stitch sewing machine, having, in combination, stitch forming devices including a hook needle, an awl, a loop taker, a take-up, continuously rotating cranks, and lever and link connections between the cranks and awl and take-up.

14. A wax thread lock stitch sewing machine, having, in combination, stitch forming devices including a hook needle, a loop taker, a take-up, means for actuating the take-up, a continuously rotating crank, and lever and link connections between the crank and needle acting to cause the needle to dwell at the completion of its backward stroke.

15. A wax thread lock stitch sewing machine, having, in combination, stitch forming devices including a hook needle, a loop taker, a take-up, means for actuating the take-up, a continuously rotating crank, and lever and link connections between the crank and needle acting to impart an idle forward and backward movement to the needle near the limit of its backward stroke.

16. A wax thread lock stitch sewing machine, having, in combination, stitch forming devices including a hook needle, a loop taker, a take-up, means for actuating the take-up, a continuously rotating crank, and lever and link connections between the crank and needle acting to cause the needle to dwell near the limit of its forward stroke.

17. A wax thread lock stitch sewing machine, having, in combination, stitch forming devices including a hook needle, a loop taker, a take-up, means for actuating the take-up, a continuously rotating crank, and lever and link connections between the crank and needle acting to impart an idle forward and backward movement to the needle near the limit of its backward stroke and acting

to cause the needle to dwell near the limit of its forward stroke.

18. A wax thread lock stitch sewing machine, having, in combination, stitch forming devices including a hook needle, a loop taker, a take-up, means for actuating the take-up, a continuously rotating crank, and lever and link connections between the crank and needle acting to cause the needle to dwell near the limits of both its forward and backward strokes.

19. A wax thread lock stitch sewing machine, having, in combination, stitch forming devices including a hook needle, a needle carrier, a loop taker, a take-up, a continuously rotating crank, and connections for actuating the needle carrier from the crank including an intermediate pivoted lever and a link connection from the lever to the needle carrier.

20. A wax thread lock stitch sewing machine, having, in combination, stitch forming devices including a hook needle, a needle carrier, a loop taker, a take-up, a continuously rotating crank, and connections for actuating the needle carrier from the crank including a plurality of pivoted levers, link connection between the levers, and link connections between the levers and the crank and needle carrier.

21. A wax thread lock stitch sewing machine, having, in combination, stitch forming devices including a hook needle, a needle carrier, a loop taker, a take-up, a continuously rotating crank, a bell crank, a link connecting the rotating crank and one arm of the bell crank, a second bell crank, a link connecting the other arm of the first bell crank and one arm of the second bell crank, and a link connecting the other arm of the second bell crank and the needle carrier.

22. A wax thread lock stitch sewing machine, having, in combination, stitch forming devices including a hook needle, a needle carrier, a loop taker, a take-up, a continuously rotating crank, and connections for actuating the needle carrier from the crank including an oscillating arm, connections between the arm and the needle carrier including a link connected to the free end of the arm, and connections between the arm and crank acting to move the free end of the arm through a dead center position to impart an idle forward and backward movement to the needle near the limit of its backward stroke.

23. A wax thread lock stitch sewing machine, having, in combination, stitch forming devices including a hook needle, a needle carrier, a loop taker, a take-up, a continuously rotating crank, and connections for actuating the needle carrier from the crank including an oscillating arm, connections between the arm and needle carrier includ-

ing a link connected to the free end of the arm, and connections between the arm and crank acting to move the free arm to an approximately dead center position to cause the needle to dwell near the limit of its forward stroke.

24. A wax thread lock stitch sewing machine, having, in combination, stitch forming devices including a hook needle, an awl, a loop taker, a take-up, means for actuating the take-up and needle, a continuously rotating crank, and lever and link connections between the crank and awl acting to cause the awl to dwell at the completion of its forward stroke.

25. A wax thread lock stitch sewing machine, having, in combination, stitch forming devices including a hook needle, an awl, a loop taker, a take-up, means for actuating the take-up and needle, a continuously rotating crank, and connections between the crank and awl acting to impart an idle backward and forward movement to the awl near the limit of its forward stroke.

26. A wax thread lock stitch sewing machine, having, in combination, stitch forming devices including a hook needle, an awl, an awl carrier, a loop taker, a take-up, a continuously rotating crank, and connections for actuating the awl carrier from the crank including an oscillating arm, a link between the arm and awl carrier, and connections between the arm and crank acting to carry the connecting point between the arm and link beyond a dead center position to impart an idle backward and forward movement to the awl near the limit of its forward stroke.

27. A wax thread lock stitch sewing machine, having, in combination, stitch forming devices including a hook needle, an awl, an awl carrier, a loop taker, a take-up, a continuously rotating crank, and connections for actuating the awl carrier from the crank including an oscillating arm, connections between the arm and awl carrier including a link connected to the free end of the arm and connections between the arm and crank acting to move the free end of the arm through a dead center position to impart an idle backward and forward movement to the awl near the limit of its forward stroke.

28. A wax thread lock stitch sewing machine, having, in combination, stitch forming devices including a hook needle, a continuously rotating loop taker making three complete rotations during each cycle of operations of the machine, an oscillating take-up arm, and a continuously rotating crank for operating the take-up arm.

29. A wax thread lock stitch sewing machine, having, in combination, stitch forming devices including a needle, a loop taker, an oscillating take-up arm movable to an

approximately central position with relation to the loop which it draws out and oscillating in a plane parallel to the plane of the loop, and a continuously rotating crank for operating the take-up.

30. A wax thread lock stitch sewing machine, having, in combination, stitch forming devices including a needle, a loop taker, an oscillating take-up arm movable to an approximately central position with relation to the loop which it draws out and oscillating in a plane parallel to the plane of the loop, a continuously rotating crank, and connections between the take-up arm and crank acting to impart a dwell to the take-up arm near the limit of its backward stroke.

31. A wax thread lock stitch sewing machine, having, in combination, stitch forming devices including a needle, a loop taker, an oscillating take-up arm movable to an approximately central position with relation to the loop which it draws out, a continuously rotating crank, and connections for oscillating the take-up arm from the crank including an intermediately pivoted lever.

32. A wax thread lock stitch sewing machine, having, in combination, stitch forming devices including a needle, a loop taker, an oscillating take-up arm movable to an approximately central position with relation to the loop which it draws out, a continuously rotating crank, and connections for actuating the take-up arm from the crank including an intermediate rock shaft.

33. A wax thread lock stitch sewing machine, having, in combination, stitch forming devices including a needle, a loop taker, an oscillating take-up arm movable to an approximately central position with relation to the loop which it draws out, a continuously rotating crank, and connections for oscillating the take-up arm from the crank comprising an intermediate rock shaft provided with two arms, a link connecting one of the arms with the crank, and a link connecting the other arm with the take-up.

34. A wax thread lock stitch sewing machine, having, in combination, stitch forming devices including a needle, a continuously rotating loop taker making three complete revolutions during each cycle of stitch forming operations of the machine, a take-up, a continuously rotating crank, and connections for actuating the take-up from the crank operating in timed relation to the loop taker and acting to impart a complete loop drawing movement to the take-up in less than one-fourth the time of a cycle of stitch forming operations.

35. A wax thread lock stitch sewing machine, having, in combination, a hook needle, a loop taker, an oscillating take-up

arm, a continuously rotating crank for actuating the take-up arm, a thread detainer, and mechanism for positively moving the thread detainer with relation to 5 the take-up arm to coöperate with the take-up in controlling the thread.

36. A wax thread lock stitch sewing machine, having, in combination, stitch forming devices including a hook needle, a 10 thread finger, a looper, a loop taker, an oscillating take-up arm, a continuously rotating crank for actuating the take-up arm, a slack thread controlling device mounted independently of the take-up arm, and 15 means for positively actuating said device to coöperate with the take-up in controlling the thread.

37. A wax thread lock stitch sewing machine, having, in combination, stitch forming devices, including a hook needle, a loop 20 taker, an oscillating take-up arm, a continuously rotating crank for actuating the take-up arm, a thread detainer and mechanism for positively moving the thread 25 detainer relatively to the take-up to cause the thread detainer to engage the loop of thread drawn out by the take-up and hold the loop during the retractive movement of the take-up arm.

38. A wax thread lock stitch sewing machine, having, in combination, stitch forming devices, including a hook needle, a loop 30 taker, an oscillating take-up arm, a continuously rotating crank for actuating the 35 take-up arm, a thread detainer and mechanism for positively moving the thread detainer with relation to the take-up to engage and hold the loop of thread drawn out by the take-up and to release the loop 40 after the needle has drawn the thread into the work.

39. A wax thread lock stitch sewing machine, having, in combination, stitch forming devices including a hook needle, a loop 45 taker, an oscillating take-up arm, a continuously rotating crank for actuating the take-up arm, a thread detainer comprising a thread engaging finger, a rock shaft upon which said finger is mounted, and mechanism 50 for oscillating the rock shaft to cause the finger to enter and engage the loop of thread drawn out by the take-up.

40. A wax thread lock stitch sewing machine, having, in combination, stitch forming devices including a hook needle, a thread 55 finger, a loop taker, an oscillating take-up arm, a continuously rotating crank for actuating the take-up arm, and a thread detainer comprising a thread engaging finger 60 and mechanism for positively moving said finger with relation to the take-up arm to engage the loop of thread drawn out by the take-up, and for moving the said finger to supply thread for the formation of the 65 thread finger loop, and to release the thread

after the needle has drawn the thread into the work.

41. A wax thread lock stitch sewing machine, having, in combination, stitch forming devices including a hook needle, a thread 70 finger, a looper, a loop taker, an oscillating take-up arm, a continuously rotating crank for actuating the take-up arm, a thread detainer, and means for positively moving the thread detainer with relation to the take-up 75 arm to supply thread for the formation of the thread finger loop.

42. A wax thread lock stitch sewing machine, having, in combination, stitch forming devices including a hook needle, a thread 80 finger, a looper, a hook needle, a loop taker, an oscillating take-up arm, a continuously 85 rotating crank for actuating the take-up arm, a thread detainer, and mechanism for positively moving the thread detainer with relation to the take-up arm to engage the loop of thread drawn out by the take-up, to hold the thread during the retraction of the take-up arm, and to deliver the thread to the thread finger and looper. 90

43. A sewing machine, having, in combination, stitch forming devices including a hook needle and a thread finger, a rock shaft carrying the thread finger, and means for oscillating the rock shaft comprising a 95 sliding element, a link connecting the rock shaft and said element, and a cam directly engaging said element for reciprocating said element.

44. A sewing machine, having, in combination, stitch forming devices including a hook needle, and a looper, a looper arm, an oscillating carrier in which the looper arm is loosely mounted to oscillate about a pivot parallel to the pivot of the carrier, a cam 100 actuated sliding element connected to and adapted to oscillate the looper arm with relation to the carrier, and a second cam actuated element connected to and adapted to oscillate the carrier, whereby a compound 105 motion is imparted to the looper.

45. A sewing machine, having, in combination, stitch forming devices including a hook needle, a thread finger, and a looper 110 coöperating therewith to lay the thread in the hook of the needle, and a cam actuated sliding element connected to and adapted to oscillate the thread finger, an oscillating carrier, a looper arm mounted in said carrier and adapted to oscillate with relation thereto about a pivot parallel to the pivot of the carrier, a second cam actuated sliding element connected to and adapted to oscillate said looper arm with relation to the carrier, and a third cam actuated sliding 115 element connected to and adapted to oscillate the carrier.

46. A wax thread lock stitch sewing machine having, in combination, stitch forming devices including a hook needle, a take- 120

up, and a continuously rotating loop-taking hook having an inwardly directed loop-taking beak.

47. A wax thread lock stitch sewing machine, having, in combination, a work support, stitch forming devices, including a hook needle, a take-up, and a continuously rotating loop-taking hook supported on the same side of the work support as the needle and comprising a cylindrical body provided with an inwardly directed loop-taking beak.

48. A wax thread lock stitch sewing machine having, in combination, stitch forming devices including a hook needle, a take-up, a rotary loop taking hook comprising a cylindrical body provided with an inwardly directed loop-taking beak and means for peripherally supporting and driving the hook.

49. A wax thread lock stitch sewing machine having, in combination, a work support, stitch forming devices including a hook needle, a take-up and a loop-taking hook supported on the same side of the work support as the needle and comprising a cylindrical body provided with an inwardly directed loop-taking beak and means for peripherally supporting and driving the hook.

50. A wax thread lock stitch sewing machine having, in combination, a work support, stitch forming devices including a take-up, a bobbin case, a rotary loop-taking hook comprising a cylindrical body surrounding and supporting the bobbin case and provided with an inwardly directed loop-taking beak, and a hook needle supported on the same side of the work support as the hook and arranged to pass between the bobbin case and the hook body and means for peripherally supporting and driving the hook.

51. A wax thread lock stitch sewing machine, having, in combination, a work support, and stitch forming devices including a hook needle, a take-up, a loop taker supported on the same side of the work support as the needle and comprising a cylindrical body formed with an inwardly directed loop taking beak and having provision for the passage of the needle through the interior of the hook body.

52. A wax thread lock stitch sewing machine, having, in combination, a work support, and stitch forming devices including a hook needle, a take-up, a loop taker supported on the same side of the work support as the needle and comprising a cylindrical body provided with an inwardly directed loop taking beak, and a stationary bobbin case supported on the interior of the hook and having a part cut away for the passage of the needle between the bobbin case and the hook body.

53. A wax thread lock stitch sewing ma-

chine, having, in combination, stitch forming devices including a hook needle, a take-up, a bobbin case, a loop taking hook supporting the bobbin case and having a loop taking beak and a thread receiving groove formed on the interior thereof, the thread receiving groove being longer than the thickness of the bobbin case, whereby the loop of thread engaged by the beak is expanded to a greater width than the thickness of the bobbin case.

54. A wax thread lock stitch sewing machine, having, in combination, a horizontal work support, stitch forming devices including a straight hook needle, a take-up, and a rotary loop taker supported on the same side of the work support as the needle and operating in a plane inclined at an angle of about 60° to the axis of the needle.

55. A wax thread lock stitch sewing machine, having, in combination, a horizontal work support, stitch forming devices including a hook needle, a stationary bobbin case supported below and at the rear of the work support and having an upwardly opening cup-shaped bobbin receiving recess, a detent plate lying above the bobbin case and having an opening over the bobbin receiving recess and a cover plate hinged below and at the rear of the work support to cover and protect the bobbin case and to allow easy access thereto.

56. A wax thread lock stitch sewing machine having, in combination, a work support, stitch forming devices including a hook needle, a take-up, a bobbin case having a closed lower end directed toward the needle and provided with an open upper end and a loop taking hook supporting the bobbin case and provided with an open upper end concentric with the upper end of the bobbin case whereby a bobbin can be inserted and removed through the upper end of the hook.

57. A wax thread lock stitch sewing machine, having, in combination, a hook needle, a take-up, a bobbin case, a rotary loop taker supporting the bobbin case and arranged to impart a tilting movement thereto, and detent means actuated by the tilting movement of the bobbin case to hold the bobbin case from rotating with the loop taker.

58. A wax thread lock stitch sewing machine, having, in combination, a hook needle, a take-up, a bobbin case, a rotary loop taker supporting the bobbin case in a plane lying at an angle to the plane of rotation of the loop taker whereby the rotation of the loop taker imparts a tilting movement to the bobbin case, and a plurality of stationary detents with which the bobbin case is adapted to be brought into engagement by said tilting movement to hold the bobbin case from rotating with the loop taker.

59. A wax thread lock stitch sewing ma-

chine, having, in combination, a hook needle, a take-up, a discoidal bobbin case having recesses formed on one face thereof, a rotary loop taker comprising a cylindrical body 5 portion having an interior circular bearing supporting the bobbin case in a plane inclined to the plane of rotation of the loop taker whereby the rotation of the loop taker imparts a tilting movement to the bobbin case, and stationary detent pins with which the recesses are brought into coöperating engagement by the tilting movement of the bobbin case to hold the bobbin case from rotating with the loop taker.

15 60. A wax thread lock stitch sewing machine, having, in combination, a hook needle, a take-up, a discoidal bobbin case having recesses formed near the edges of its upper face, a rotary loop taker comprising a cylindrical body portion and a loop taking beak and having a circular bearing formed on the interior of the body portion rotatably supporting the bobbin case in a plane extending obliquely upward from the beak at 20 an angle to the plane of rotation of the loop taker whereby the rotation of the loop taker imparts a tilting movement to the bobbin case, and a fixed plate lying above the loop taker in a plane parallel to the plane of rotation of the loop taker and having downwardly projecting detent pins, the recesses at the edge of the bobbin case momentarily opposite the beak being lifted by the tilting of the bobbin case into engagement with the 25 detent pins to hold the bobbin case from rotating with the loop taker, and the recesses at the edge of the bobbin case momentarily next the beak being lowered by the tilting of the bobbin case from engagement with the 30 detent pins to provide a thread clearance space between the edge of the bobbin case and plate.

35 61. A wax thread lock stitch sewing machine, having, in combination, a work support, stitch forming devices including a take-up, a straight hook needle, a rotary loop taking hook supported on the same side of the work support as the needle, rotating in a plane inclined to the path of the needle therethrough, operating in timed 40 relation to the needle and making a plurality of complete rotations during each cycle of stitch forming operations, said loop taking hook having an inwardly directed 45 loop taking beak and having provision for the passage of the needle through the interior of the hook body, a pivoted frame supporting the hook, and means operating in timed relation to the needle and hook for 50 oscillating the frame to change the path of the beak with relation to the needle to cause the beak to enter the loop of needle thread during one of said plurality of rotations and clear the needle during another 55 rotation.

62. A wax thread lock stitch sewing machine, having, in combination, a work support, stitch forming devices including a take-up, a hook needle, a rotary loop taking hook supported on the same side of the 70 work support as the needle, operating in timed relation thereto and making a plurality of complete rotations during each cycle of stitch forming operations, said loop taking hook having an inwardly directed 75 loop taking beak and having provision for the passage of the needle through the interior of the hook body, and means operating in timed relation to the needle for moving the hook to bring the path of the beak 80 across the end of the needle to cause the beak to enter the loop of thread drawn out by the retractive movement of the needle through the hook body, and to bring the path of the beak at one side of the needle 85 while the needle is passing through the interior of the hook body.

63. A wax thread lock stitch sewing machine, having, in combination, a work support, stitch forming devices including a 90 take-up, a rotary loop-taker making a plurality of complete rotations during each cycle of stitch forming operations and having a loop taking beak, a hook needle supported on the same side of the work support as the 95 loop taker and arranged to pass through the plane of rotation of the loop taker at a substantially large angle to said plane and through the work support, a movable frame supporting the loop taker, and means operating in timed relation to the needle and 100 hook for moving the frame to cause the beak to pass through the axis of the needle after the needle has drawn out its loop of thread, and to pass at one side of the needle 105 when the needle is moving through the plane of rotation of the loop taker.

64. A wax thread lock stitch sewing machine, having, in combination, a work support, stitch forming devices including a 110 take-up, a hook needle, a rotary loop taking hook supported on the same side of the work support as the needle, rotating in a plane lying at a substantially large angle to the path of the needle therethrough, operating in timed relation to the needle and making a plurality of complete rotations during each cycle of stitch forming operations, said loop taking hook comprising a cylindrical body portion having an inwardly directed 115 loop taking beak and having provision for the passage of the needle through the interior of said cylindrical body portion, and means operating in timed relation to the needle and hook for reciprocating the 120 hook laterally to move its axis of rotation away from the path of the needle and cause the beak to enter the loop of thread drawn out by the needle, and to move its axis of rotation toward the path of the needle and 125 130

cause the beak to encircle the needle while the needle is passing through the interior of the hook body.

65. A wax thread lock stitch sewing machine, having, in combination, a work support, stitch forming devices including a take-up, a hook needle, a bobbin case, a rotary loop taker arranged to pass the needle thread about the bobbin case, operating in timed relation to the needle and making a plurality of complete revolutions during each cycle of stitch forming operations, an oscillating frame supporting the loop taker, and means for oscillating the frame including a continuously rotating shaft, a cam plate mounted on the shaft and inclined to its axis, a ring lying against the cam plate, a gimbal-like mounting for the ring, and connections between said mounting and the oscillating frame.

66. A wax thread lock stitch sewing machine, having, in combination, a work support, stitch forming devices including a take-up, a hook needle, a bobbin case, a rotary loop taker arranged to pass the needle thread about the bobbin case, operating in timed relation to the needle and making a plurality of complete revolutions during each cycle of stitch forming operations, an oscillating frame supporting the loop taker, and means for oscillating the frame comprising a continuously rotating shaft, a cam plate mounted on the shaft and inclined to its axis, a ring mounted on the main frame to oscillate about an axis lying at right angles to and intersecting the axis of the shaft, a link connection between said ring and the movable frame, and a second ring supported in the first ring and free to oscillate about an axis lying at right angles to and intersecting the axis of oscillation of the first ring, said second ring lying against and receiving a wobbling motion from the cam plate.

67. A wax thread lock stitch sewing machine, having, in combination, a work support, stitch forming devices, including a take-up, a rotary loop taker operating in timed relation to the needle and making a plurality of complete revolutions during each cycle of stitch forming operations, a hook needle supported on the same side of the work support as the loop taker and arranged to pass through the plane of rotation of the loop taker and through the work support, an oscillating frame pivotally mounted upon the frame of the machine for supporting the loop taker, means for oscillating said frame, and means for rotating the loop taker comprising a universal joint situated in the axis about which said frame pivots.

68. A wax thread lock stitch sewing machine, having, in combination, a work support, stitch forming devices including a

hook needle, a take-up, a bobbin case mounted below the work support and having its lower end closed, a loop taking hook to carry the loop of needle thread around the bobbin case, and a manually operable bobbin ejecting device arranged to operate through an opening in the closed end of the bobbin case.

69. A wax thread lock stitch sewing machine, having, in combination, a work support, stitch forming devices including a hook needle, a take-up, a loop taking hook situated below the work support, a movable supporting frame for the hook, a bobbin case supported by the hook and having its lower end closed, and a manually operable bobbin ejecting device comprising a plunger arranged to operate through an opening in the closed end of the bobbin case, a pinion to elevate the plunger, and means for turning the pinion comprising a handle on the machine frame and connections including a universal joint between the pinion and the handle.

70. A lock stitch sewing machine having in combination, stitch forming devices including a hook needle, a stationary bobbin case formed with a cup-shaped bobbin receiving recess and bearing stud projecting from the bottom of the recess, a bobbin having a central aperture by which it is journaled on the stud, said stud having a central recess and a transverse slot cut in its top, the slot having an enlarged lower portion, a latch piece received in the slot and having a nose engaging over the edge of the bobbin aperture and having a flange engaging in the enlarged lower portion of the slot, said flange being thinner than the depth of said enlarged portion, a compression spring in the recess of the stud pressing on the latch piece and holding the flange against the shoulder forming the top of the enlarged portion of the slot to hold the nose in yielding engagement with the edge of the bobbin aperture and a rotary loop-taking hook to carry the loop of needle thread above the bobbin case.

71. A lock stitch sewing machine having in combination, stitch forming devices including a hook needle, a stationary bobbin case formed with a cup-shaped bobbin receiving recess and a bearing stud projecting from the bottom of the recess, a bobbin having a central aperture by which it is journaled on the stud, said stud having a central recess and a transverse slot cut in its top, the slot being of a T-shaped cross section with the enlarged portion at the bottom, a latch piece received in the slot, having a nose engaging over the edge of the bobbin aperture and having flanges engaging in the enlarged lower portion of the slot, the ends of the flanges opposite the nose being thinner than the depth of said enlarged portion, a

- compression spring in the recess of the stud pressing on the latch piece and holding the flanges against the shoulders forming the top of the enlarged portion of the slot to hold the nose in yielding engagement with the edge of the bobbin aperture and a rotary loop-taking hook to carry the loop of needle thread above the bobbin case.
72. A wax thread lock stitch sewing machine, having, in combination, stitch forming devices including a hook needle, a stationary bobbin case having a bobbin receiving recess, one side of the recess being cut away to form an open-topped opening, for the passage of the thread, a tension spring mounted within the recess and having an upwardly extending finger pressing against the wall of the recess at one side of said opening and behind which the thread can be slipped, whereby the bobbin case may be threaded before the bobbin is inserted in the case, and a rotary loop taking hook to carry the loop of needle thread about the bobbin case.
73. A wax thread lock stitch sewing machine, having, in combination, stitch forming devices including a hook needle, a stationary bobbin case having a cup-shaped upwardly opening bobbin receiving recess, one wall of the recess being cut away to form an open-topped opening for the passage of the bobbin thread, a thread tension spring comprising an upwardly extending finger pressing against the wall of the recess at one side of said opening and behind which the thread can be slipped, a thread guiding eye on the bobbin case outside the opening provided with a threading slot, whereby the bobbin case may be threaded before the bobbin is inserted in the case, and a rotary loop taking hook to carry the loop of needle thread over the bobbin case.
74. A wax thread lock stitch sewing machine, having, in combination, stitch forming devices including a straight hook needle, a take-up, and a rotary loop taking hook provided with an inwardly directed loop taking beak and arranged to rotate in a plane inclined to the path of movement of the needle.
75. A wax thread lock stitch sewing machine having, in combination, a horizontal work support, stitch forming devices including a straight hook needle, a take-up, and a rotary loop taking hook provided with an inwardly directed loop taking beak and arranged to rotate in a plane inclined at an angle of about 60° to the axis of the needle.
76. A wax thread lock stitch sewing machine having, in combination, stitch forming devices including a hook needle, a rotary loop taking hook provided with an inwardly directed loop taking beak, means for imparting a plurality of complete rotations to the hook during each cycle of stitch forming operations, and means for moving the hook

to cause the beak of the hook to intersect the path of motion of the needle during one of its plural rotations and lie outside of the path of motion of the needle during the other rotation or rotations.

77. A wax thread lock stitch sewing machine having, in combination, stitch forming devices including a hook needle, a rotary loop taking hook provided with an inwardly directed loop taking beak and arranged to rotate in a plane inclined to the path of motion of the needle, means for imparting to the hook a plurality of complete rotations during each cycle of stitch forming operations, and means for oscillating the hook about a line parallel to its plane of rotation to cause the beak of the hook to engage the needle loop and then recede from the path of the needle.

78. In a sewing machine, the combination with the main-shaft, an actuating crank or eccentric fixed thereon, and a reciprocating needle-bar carrying a needle, of a plural-armed rocker, a pitman connection between one arm of said rocker and the actuating crank or eccentric, a rock-shaft provided with two crank-arms, a connection between the other arm of said rocker and an arm of said rock-shaft, and a pitman connection between the second arm of said rock-shaft and the needle bar, the second named crank-arm being so set upon said rock-shaft that in one extreme position it carries the link connection with the needle bar into and out of substantial parallelism with itself.

79. A wax thread lock stitch sewing machine having in combination, stitch forming devices including a hook needle, a loop-taker, a take-up, an awl acting during each cycle of stitch forming operations to enter the work after the take-up has operated to set the stitch, means for actuating the take-up, and continuously rotating cranks for actuating the needle and awl.

80. A wax thread lock stitch sewing machine having in combination, stitch forming devices including a hook needle, a loop-taker, a take-up, an awl acting during each cycle of stitch forming operations to enter the work after the take-up has operated to set the stitch, means for actuating the take-up and awl, and a continuously rotating crank for actuating the needle.

81. A wax thread lock stitch sewing machine having in combination, stitch forming devices including a hook needle, a loop-taker, a take-up, an awl acting during each cycle of stitch forming operations to enter the work after the take-up has operated to set the stitch, means for actuating the take-up and needle, and a continuously rotating crank for actuating the awl.

82. A wax thread lock stitch sewing machine having in combination, stitch forming devices including a hook needle, a loop-

taker, a take-up, an awl, means for actuating the take-up, and continuously rotating cranks for actuating the needle and awl acting to move the points of the needle and awl toward and from each other to cause the awl to leave the work as the needle enters the work.

83. A wax thread lock stitch sewing machine having in combination, stitch forming devices including a hook needle, a loop-taker, a take-up, an awl acting during each cycle of stitch forming operations to enter the work after the take-up has operated to set the stitch, means for actuating the take-up, and continuously rotating cranks for actuating the needle and awl acting to move the

points of the needle and awl toward and from each other to cause the awl to leave the work as the needle enters the work.

84. A wax thread lock stitch sewing machine having in combination, stitch forming devices including a hook needle, a loop-taker, a take-up, an awl acting during each cycle of stitch forming operations to enter the work after the take-up has operated to set the stitch, means for actuating the needle and awl, and a continuously rotating crank for actuating the take-up.
